(57) **ABSTRACT**

An ink jet system includes a head unit that includes a nozzle discharging ink, a pressure chamber communicating with the nozzle, and a drive element applying pressure fluctuation to the ink in the pressure chamber by supplying a drive pulse, an acquisition portion that acquires output information including one or both of first output information regarding the head unit and second output information regarding the ink used for the head unit, a first coupling portion that is communicably network-coupled to a server, a first output portion that outputs the output information to the server via the first coupling portion, a first input portion to which input information is input from the server via the first coupling portion, and a determination portion that determines a drive timing of the drive element based on the input information.

INK JET SYSTEM

The present application is based on, and claims priority from JP Application Serial Number 2021-193099, filed Nov. 29, 2021, the disclosure of which is hereby incorporated by reference herein in its entirety.

BACKGROUND

1. Technical Field

The present disclosure relates to an ink jet system.

2. Related Art

In an ink jet printer, normally, ink is discharged from a head to a medium while scanning the head against the medium (for example, refer to JP-A-2011-121208).

In recent years, there is a business model in which a head manufacturer manufactures and sells a head to a printer manufacturer. Printers have various applications and demands. In the above business model, the head manufacturer provides the head to the printer manufacturer in cooperation with the printer manufacturer who has specialized knowledge for each application and each demand. The printer manufacturer utilizes the above-described specialized knowledge to manufacture a printer incorporating the head of the head manufacturer. This is because there are cases where the above business model is more efficient in terms of comprehensively satisfying various applications and demands than the head manufacturer manufactures printers that satisfy various applications and demands one by one.

However, in the above business model, it was necessary for the printer manufacturer to search for and determine an optimum recording condition (drive timing, scanning speed, gap between head and medium, and the like) for achieving an ideal landing position. Depending on the printer manufacturer, there are cases where there is specialized knowledge for each application and each demand, but there is not much knowledge about the printer itself, and in that case, this search and determination takes a huge amount of time and cost.

On the other hand, especially when the head manufacturer has knowledge about the printer, it is conceivable that the head manufacturer provides appropriate information on the recording condition to the printer manufacturer. However, due to the nature of the above-described business model that the head manufacturer and the printer manufacturer are different, it is unclear on the head manufacturer side how the printer manufacturer sets the usage conditions of ink, temperature, head, and the like. Since the optimum recording condition differs according to these usage conditions, it was difficult for the head manufacturer to provide the appropriate information on the recording condition. Therefore, the printer manufacturer is required to search for the information on the recording condition by himself or herself according to each usage condition, and in some cases, the burden on the printer manufacturer may increase.

SUMMARY

According to an aspect of the present disclosure, there is provided an ink jet system including a head unit that includes a nozzle discharging ink, a pressure chamber communicating with the nozzle, and a drive element applying pressure fluctuation to the ink in the pressure chamber by

2

supplying a drive pulse, an acquisition portion that acquires output information including one or both of first output information regarding the head unit and second output information regarding the ink used for the head unit, a first coupling portion that is communicably network-coupled to a server, a first output portion that outputs the output information to the server via the first coupling portion, a first input portion to which input information is input from the server via the first coupling portion, and a determination portion that determines a drive timing of the drive element based on the input information.

According to another aspect of the present disclosure, there is provided an ink jet system including a head unit that includes a nozzle discharging ink, a pressure chamber communicating with the nozzle, and a drive element applying pressure fluctuation to the ink in the pressure chamber by supplying a drive pulse, an acquisition portion that acquires output information including one or both of first output information regarding the head unit and second output information regarding the ink used for the head unit, a first coupling portion that is communicably network-coupled to a server, a first output portion that outputs the output information to the server via the first coupling portion, a first input portion to which input information is input from the server via the first coupling portion, and a determination portion that determines a scanning speed of the head unit based on the input information.

According to still another aspect of the present disclosure, there is provided an ink jet system including a head unit that includes a nozzle discharging ink, a pressure chamber communicating with the nozzle, and a drive element applying pressure fluctuation to the ink in the pressure chamber by supplying a drive pulse, an acquisition portion that acquires output information including one or both of first output information regarding the head unit and second output information regarding the ink used for the head unit, a first coupling portion that is communicably network-coupled to a server, a first output portion that outputs the output information to the server via the first coupling portion, a first input portion to which input information is input from the server via the first coupling portion, and a determination portion that determines a gap between the head unit and a medium based on the input information.

BRIEF DESCRIPTION OF THE DRAWINGS

FIG. 1 is a schematic diagram illustrating a configuration example of an ink jet system according to a first embodiment.

FIG. 2 is a schematic diagram illustrating a configuration example of an ink discharge device used in the ink jet system according to the first embodiment.

FIG. 3 is a cross-sectional view illustrating a configuration example of a head chip.

FIG. 4 is a schematic diagram illustrating a configuration example of a first processing device used in the ink jet system according to the first embodiment.

FIG. 5 is a schematic diagram illustrating a configuration example of a server used in the ink jet system according to the first embodiment.

FIG. 6 is a flowchart illustrating processing of the ink jet system according to the first embodiment.

FIG. 7 is a table for describing information illustrating a correspondence relationship between output information and first input information of information included in correspondence information.

FIG. 8 is a diagram for describing a drive timing based on the first input information.

FIG. 9 is a table for describing information illustrating a correspondence relationship between the output information and second input information of the information included in the correspondence information.

FIG. 10 is a diagram for describing a scanning speed based on the second input information.

FIG. 11 is a table for describing information illustrating a correspondence relationship between the output information and third input information of the information included in the correspondence information.

FIG. 12 is a diagram for describing a gap based on the third input information.

FIG. 13 is a schematic diagram illustrating a configuration example of an ink jet system according to a second embodiment.

FIG. 14 is a schematic diagram illustrating a configuration example of an ink discharge device used in the ink jet system according to the second embodiment.

FIG. 15 is a flowchart illustrating processing of the ink jet system according to the second embodiment.

FIG. 16 is a schematic diagram illustrating a configuration example of an ink jet system according to a third embodiment.

FIG. 17 is a schematic diagram illustrating a configuration example of a second processing device used in the ink jet system according to the third embodiment.

FIG. 18 is a flowchart illustrating processing of the ink jet system according to the third embodiment.

FIGS. 19A and 19B are diagrams for describing a transition of display of the second processing device.

FIGS. 20A and 20B are diagrams for describing a transition of display of the second processing device.

FIG. 21 is a schematic diagram illustrating a configuration example of an ink jet system according to a fourth embodiment.

FIG. 22 is a schematic diagram illustrating a configuration example of an ink discharge device used in the ink jet system according to the fourth embodiment.

FIG. 23 is a flowchart illustrating processing of the ink jet system according to the fourth embodiment.

DESCRIPTION OF EXEMPLARY EMBODIMENTS

Hereinafter, preferred embodiments according to the present disclosure will be described with reference to the accompanying drawings. In the drawings, the dimensions and scale of each part are appropriately different from the actual ones, and some parts are schematically illustrated for easy understanding. In addition, the scope of the present disclosure is not limited to these forms unless it is stated in the following description that the present disclosure is particularly limited.

1. First Embodiment

1-1. Overview of Ink Jet System

FIG. 1 is a schematic diagram illustrating a configuration example of an ink jet system 10 according to a first embodiment. The ink jet system 10 is a system that prints by an ink jet method. In particular, the ink jet system 10 has a function of determining a recording condition used for the printing. As will be described in detail later, the "recording condition" is a condition that allows a landing position of the ink on the medium to be changed, and are, for example, a drive timing

of the head (ink discharge timing), a scanning speed of the head, and a gap between the head and the medium, which will be described later.

In the example illustrated in FIG. 1, the ink jet system 10 includes ink discharge devices 100_1 to 100_3, first processing devices 200_1 to 200_3, a server 300, and a third processing device 400.

Here, the ink discharge devices 100_1 to 100_3 are provided by the manufacturer of the printer main body, which will be described later. The ink discharge devices 100_1 to 100_3 may be provided by the same manufacturer or may be provided by different manufacturers. Each of the first processing devices 200_1 to 200_3 may be owned by the user or may be provided by the manufacturer of the printer main body. On the other hand, the head unit 110 incorporated in each of the ink discharge devices 100_1 to 100_3 is provided by a head manufacturer described later. Each of the server 300 and the third processing device 400 is owned by the head manufacturer. Maintenance and management of the server 300 are performed by the head manufacturer.

When the user uses the printer main body, the user owns the ink discharge device 100_1, the first processing device 200_1, and the head unit 110. On the other hand, although the user does not own the server 300, the first processing device 200_1 is communicably coupled to the server 300 via the communication network NW.

The user refers to a person who uses the ink discharge device 100_1. For example, when a manufacturer of the printer main body who purchased a head from a head manufacturer and manufactured the printer main body uses the printer main body, the manufacturer of the printer main body is the user. In addition, for example, when a manufacturer of the printer main body purchases a head from a head manufacturer and manufactures a printer main body, and a third party purchases and uses the printer main body from the manufacturer of the printer main body, the third party is a user.

The ink discharge device 100_1 is communicably coupled to the first processing device 200_1. The ink discharge device 100_2 is communicably coupled to the first processing device 200_2. The ink discharge device 100_3 is communicably coupled to the first processing device 200_3. As described above, the ink discharge devices 100_1 to 100_3 correspond to each of the first processing devices 200_1 to 200_3, and are communicably coupled to the first processing devices 200_1 to 200_3. In the following, each of the ink discharge devices 100_1 to 100_3 may be referred to as an ink discharge device 100, without distinguishing the ink discharge devices 100_1 to 100_3. Each of the first processing devices 200_1 to 200_3 may be referred to as a first processing device 200, without distinguishing the first processing devices 200_1 to 200_3.

In the example illustrated in FIG. 1, the number of each of the ink discharge device 100 and the first processing devices 200 included in the ink jet system 10 is three, but the number is not limited thereto, and may be one, two, or four or more. That is, the set of the ink discharge device 100 and the first processing device 200 is not limited to three sets, and may be one set, two sets, or four sets or more.

The ink discharge device 100 is a serial type printer that prints an image based on the recorded data DP from the first processing device 200 on a medium by an ink jet method. The recorded data DP is image data in a format that can be processed by the ink discharge device 100. The medium may be any medium as long as the medium can be printed by the ink discharge device 100, and is not particularly limited. For

example, various papers, various cloths, various films, and the like are included. The ink discharge device **100** may be a line type printer. In this case, second input information D2b and the elements based on the second input information D2b, which will be described later, are omitted.

The ink discharge device **100** includes a head unit **110**. The head unit **110** is a module including an ink jet head. In particular, the ink discharge device **100** is configured so that the recording condition of print processing can be changed. In the following, among the elements constituting the ink discharge device **100**, the elements other than the head unit **110** may be referred to as a "printer main body". In addition, the head unit **110** or the ink discharge head **110a** described later may be simply referred to as a "head". The configuration of the ink discharge device **100** will be described in detail later with reference to FIGS. 2 and 3.

The first processing device **200** is a computer such as a desktop type or a notebook type, and has a function of generating recorded data DP, a function of controlling printing by the ink discharge device **100**, and a function of determining the recording condition used for the printing. The configuration of the first processing device **200** will be described in detail later with reference to FIG. 4.

The first processing device **200** is communicably coupled to the server **300** via a communication network NW including the Internet. The first processing device **200** outputs output information D1 to the server **300** and inputs input information D2 from the server **300**. The output information D1 is information including one or both of the information regarding the head unit **110** described later and the information regarding the ink used for the head unit **110**. The input information D2 is information regarding the recording condition of the print processing. The first processing device **200** determines the recording condition of the print processing based on the input information D2. In addition, the first processing device **200** generates recorded data DP by image processing, for example, image data DI in a bitmap format such as JPEG or a vector system such as PostScript, portable document format (PDF), and XML paper specification (XPS). For example, the image processing includes color conversion processing, density correction processing, quantization processing, and distribution processing. In addition to the above-described processing, the image processing may include, for example, raster image processor (RIP) processing or the like, when necessary.

The server **300** is a computer that functions as a cloud server, and has a function of inputting output information D1 from the first processing device **200**, a function of generating input information D2 based on the output information D1, and a function of outputting the generated input information D2 to the first processing device **200**. The configuration of the server **300** will be described in detail later with reference to FIG. 5.

In addition, the server **300** is communicably coupled to the third processing device **400**, and appropriately transmits and receives information necessary for generating the input information D2. The third processing device **400** is a computer that inputs the output information D1 from the server **300**, when necessary, and outputs the information necessary for generating the input information D2 to the server **300**.

In the ink jet system **10** of the above outline, since the first processing device **200** outputs the output information D1 toward the server **300**, the output information D1 can be provided to the head manufacturer. Therefore, by utilizing the knowledge of the head manufacturer in addition to the output information D1, the input information D2 can be efficiently obtained as the information necessary for deter-

mining the recording condition of the print processing. Since the first processing device **200** determines the recording condition of the print processing based on the input information D2 input from the server **300**, the recording condition of the print processing can be determined while reducing the burden on the printer manufacturer. Hereinafter, the ink jet system **10** will be described in detail.

1-2. Configuration of Ink Discharge Device

FIG. 2 is a schematic diagram illustrating a configuration example of the ink discharge device **100** used in the ink jet system **10** according to the first embodiment. As illustrated in FIG. 2, the ink discharge device **100** includes a head unit **110**, a movement mechanism **120**, a communication device **130**, a storage circuit **140**, and a processing circuit **150**.

The head unit **110** is an assembly including a head chip **111**, a drive circuit **112**, a power supply circuit **113**, and a drive signal generation circuit **114**.

In the example illustrated in FIG. 2, the head unit **110** is divided into an ink discharge head **110a** including the head chip **111** and the drive circuit **112**, and a control module **110b** including the power supply circuit **113** and the drive signal generation circuit **114**. The head unit **110** is not limited to an aspect of being divided into the ink discharge head **110a** and the control module **110b**, and for example, a part or all of the control module **110b** may be incorporated in the ink discharge head **110a**.

The head chip **111** discharges ink toward the medium. In FIG. 2, among components of the head chip **111**, a plurality of drive elements **111f** are typically illustrated. A detailed example of the head chip **111** will be described later with reference to FIG. 3.

In the example illustrated in FIG. 2, the number of head chips **111** included in the head unit **110** is one, but the number may be two or more. Since the ink discharge device **100** is a serial type, one or more head chips **111** are disposed so that a plurality of nozzles are distributed over a part of the medium in the width direction. When the ink discharge device **100** is a line type, two or more head chips **111** are disposed so that a plurality of nozzles are distributed over the entire medium in the width direction.

The drive circuit **112** switches whether or not to supply a drive signal Com output from the drive signal generation circuit **114** as a drive pulse PD for each of the plurality of drive elements **111f** included in the head chip **111** under the control of the processing circuit **150**. The drive circuit **112** includes, for example, a group of switches such as a transmission gate for the switching.

The power supply circuit **113** receives power from a commercial power source (not illustrated) and generates various predetermined potentials. The various generated potentials are appropriately supplied to each part of the ink discharge device **100**. In the example illustrated in FIG. 2, the power supply circuit **113** generates a power supply potential VHV and an offset potential VBS. The offset potential VBS is supplied to the head chip **111** and the like. In addition, the power supply potential VHV is supplied to the drive signal generation circuit **114** and the like.

The drive signal generation circuit **114** is a circuit that generates the drive signal Com for driving each drive element **111f** included in the head chip **111**. Specifically, the drive signal generation circuit **114** includes, for example, a DA conversion circuit and an amplifier circuit. In the drive signal generation circuit **114**, the DA conversion circuit converts a waveform designation signal dCom described later from the processing circuit **150** from a digital signal to an analog signal, and the amplifier circuit generates a drive signal Com by amplifying the analog signal using the power

supply potential VHV from the power supply circuit 113. Here, among the waveforms included in the drive signal Com, the signal of the waveform actually supplied to the drive element 111f is the drive pulse PD.

The movement mechanism 120 changes the relative position of the head unit 110 and the medium. More specifically, since the ink discharge device 100 is a serial type, the movement mechanism 120 includes a transport mechanism that transports the medium in a predetermined direction, and a movement mechanism that repeatedly moves (scans) the head unit 110 along an axis orthogonal to the transport direction of the medium. In addition, the movement mechanism 120 is configured so that the gap between the head unit 110 and the medium can be changed. For example, a transport mechanism that transports the medium in a predetermined direction is configured so that the height of the medium transport path can be changed. When the ink discharge device 100 is a line type, the movement mechanism 120 includes a transport mechanism that transports the medium in a direction intersecting the longitudinal direction of the elongated head unit 110.

The communication device 130 is a circuit capable of communicating with the first processing device 200. For example, the communication device 130 is an interface such as a wireless or wired local area network (LAN) or a universal serial bus (USB). USB is a registered trademark. The communication device 130 may be coupled to another first processing device 200 via another network such as the Internet. In addition, the communication device 130 may be integrated with the processing circuit 150.

The storage circuit 140 stores various programs executed by the processing circuit 150 and various data such as recorded data DP processed by the processing circuit 150. The storage circuit 140 includes, for example, one or both semiconductor memories of one or more volatile memories such as a random access memory (RAM) and one or more non-volatile memories such as a read only memory (ROM), an electrically erasable programmable read-only memory (EEPROM) or a programmable ROM (PROM). The recorded data DP is supplied from, for example, the first processing device 200. The storage circuit 140 may be configured as a part of the processing circuit 150.

The processing circuit 150 has a function of controlling the operation of each part of the ink discharge device 100 and a function of processing various data. The processing circuit 150 includes, for example, one or more processors such as a central processing unit (CPU). The processing circuit 150 may include a programmable logic device such as a field-programmable gate array (FPGA) in place of the CPU or in addition to the CPU.

The processing circuit 150 controls the operation of each part of the ink discharge device 100 by executing a program stored in the storage circuit 140. Here, the processing circuit 150 generates signals such as a control signal Sk, a print data signal SI, and a waveform designation signal dCom as signals for controlling the operation of each part of the ink discharge device 100.

The control signal Sk is a signal for controlling the drive of the movement mechanism 120. The print data signal SI is a signal for controlling the drive of the drive circuit 112. Specifically, the print data signal SI specifies whether or not the drive circuit 112 supplies the drive signal Com from the drive signal generation circuit 114 to the drive element 111f as a drive pulse PD for each predetermined unit period. By this designation, the amount of ink discharged from the head chip 111 and the like are designated. The waveform designa-

nation signal dCom is a digital signal for defining the waveform of the drive signal Com generated by the drive signal generation circuit 114.

FIG. 3 is a cross-sectional view illustrating a configuration example of the head chip 111. In the following description, the X axis, Y axis, and Z axis that intersect each other are appropriately used. In the following, one direction along the X axis is the X1 direction, and the direction opposite to the X1 direction is the X2 direction. Similarly, the directions opposite to each other along the Y axis are the Y1 direction and the Y2 direction. The directions opposite to each other along the Z axis are the Z1 direction and the Z2 direction.

As illustrated in FIG. 3, the head chip 111 includes a plurality of nozzles N arranged in a direction along the Y axis. The plurality of nozzles N are divided into a first row L1 and a second row L2 which are arranged at gaps along the X axis. Each of the first row L1 and the second row L2 is a set of the plurality of nozzles N linearly arranged in the direction along the Y axis.

The head chip 111 has a configuration substantially symmetrical with each other in the direction along the X axis. However, the positions of the plurality of nozzles N in the first row L1 and the plurality of nozzles N in the second row L2 in the direction along the Y axis may be the same as or different from each other. FIG. 3 illustrates a configuration in which the positions of the plurality of nozzles N in the first row L1 and the plurality of nozzles N in the second row L2 in the direction along the Y axis coincide with each other.

As illustrated in FIG. 3, the head chip 111 includes a flow path substrate 111a, a pressure chamber substrate 111b, a nozzle plate 111c, a vibration absorber 111d, a diaphragm 111e, a plurality of drive elements 111f, a protective plate 111g, a case 111h, and a wiring substrate 111i.

The flow path substrate 111a and the pressure chamber substrate 111b are laminated in this order in the Z1 direction, and form a flow path for supplying ink to the plurality of nozzles N. The diaphragm 111e, a plurality of drive elements 111f, the protective plate 111g, the case 111h, and the wiring substrate 111i are installed in a region located in the Z1 direction with respect to a laminated body including the flow path substrate 111a and the pressure chamber substrate 111b. On the other hand, the nozzle plate 111c and the vibration absorber 111d are installed in the region located in the Z2 direction from the laminated body. Each element of the head chip 111 is approximately a plate-shaped member elongated in the Y direction, and is bonded to each other by, for example, an adhesive. Hereinafter, each element of the head chip 111 will be described in order.

The nozzle plate 111c is a plate-shaped member provided with the plurality of nozzles N in each of the first row L1 and the second row L2. Each of the plurality of nozzles N is a through-hole through which ink is passed. Here, the surface of the nozzle plate 111c facing the Z2 direction is a nozzle surface FN. The nozzle plate 111c is manufactured by processing a silicon single crystal substrate by a semiconductor manufacturing technique using a processing technique such as dry etching or wet etching, for example. However, other known methods and materials may be appropriately used for manufacturing the nozzle plate 111c. In addition, the cross-sectional shape of the nozzle is typically circular, but is not limited thereto, and may be a non-circular shape such as a polygon or an ellipse.

The flow path substrate 111a is provided with a space R1, a plurality of supply flow paths Ra, and a plurality of communication flow paths Na for each of the first row L1 and the second row L2. The space R1 is a long opening extending in the direction along the Y axis in a plan view in

the direction along the Z axis. Each of the supply flow path Ra and the communication flow path Na is a through-hole formed for each nozzle N. Each supply flow path Ra communicates with the space R1.

The pressure chamber substrate 111b is a plate-shaped member provided with a plurality of pressure chambers C called cavities for each of the first row L1 and the second row L2. The plurality of pressure chambers C are arranged in the direction along the Y axis. Each pressure chamber C is a long space formed for each nozzle N and extending in a direction along the X axis in a plan view. Each of the flow path substrate 111a and the pressure chamber substrate 111b is manufactured by processing a silicon single crystal substrate by, for example, semiconductor manufacturing technique, in the same manner as the nozzle plate 111c described above. However, other known methods and materials may be appropriately used for the manufacture of each of the flow path substrate 111a and the pressure chamber substrate 111b.

The pressure chamber C is a space located between the flow path substrate 111a and the diaphragm 111e. For each of the first row L1 and the second row L2, the plurality of pressure chambers C are arranged in a direction along the Y axis. In addition, the pressure chamber C communicates with each of the communication flow path Na and the supply flow path Ra. Therefore, the pressure chamber C communicates with the nozzle N via the communication flow path Na and communicates with the space R1 via the supply flow path Ra.

The diaphragm 111e is disposed on the surface of the pressure chamber substrate 111b facing the Z1 direction. The diaphragm 111e is a plate-shaped member that can elastically vibrate. The diaphragm 111e includes, for example, a first layer and a second layer, which are laminated in the Z1 direction in this order. The first layer is, for example, an elastic film made of silicon oxide (SiO_2). The elastic film is formed, for example, by thermally oxidizing one surface of the silicon single crystal substrate. The second layer is, for example, an insulating film made of zirconium oxide (ZrO_2). The insulating film is formed by, for example, forming a zirconium layer by a sputtering method and thermally oxidizing the layer. The diaphragm 111e is not limited to the above-described configuration by laminating the first layer and the second layer, and may be configured to include, for example, a single layer or three or more layers.

On the surface of the diaphragm 111e facing the Z1 direction, the plurality of drive elements 111f corresponding to the nozzles N are disposed with each other for each of the first row L1 and the second row L2. Each drive element 111f is a passive element that is deformed by the supply of a drive signal. Each drive element 111f has a long shape extending in a direction along the X axis in a plan view. The plurality of drive elements 111f are arranged in a direction along the Y axis so as to correspond to the plurality of pressure chambers C. The drive element 111f overlaps the pressure chamber C in a plan view.

Each drive element 111f is a piezoelectric element, and although not illustrated, each drive element 111f includes a first electrode, a piezoelectric layer, and a second electrode, and these are laminated in the Z1 direction in this order. One electrode of the first electrode and the second electrode is an individual electrode disposed apart from each other for each drive element 111f, and the drive pulse PD is supplied to the one electrode. The other electrode of the first electrode and the second electrode is a band-shaped common electrode extending in the direction along the Y axis so as to be continuous over the plurality of drive elements 111f, and an offset potential VBS is supplied to the other electrode.

Examples of the metal material of these electrodes include metal materials such as platinum (Pt), aluminum (Al), nickel (Ni), gold (Au), and copper (Cu), and among these metal materials, one type can be used alone or two or more types can be used in combination in an alloy or laminated manner. The piezoelectric layer is made of a piezoelectric material such as lead zirconate titanate ($\text{Pb}(\text{Zr},\text{Ti})\text{O}_3$), and forms, for example, a strip extending in the direction along the Y axis so as to be continuous over the plurality of drive elements 111f. However, the piezoelectric layer may be integrated over the plurality of drive elements 111f. In this case, the piezoelectric layer is provided with a through-hole penetrating the piezoelectric layer and extending in a direction along the X axis in a region corresponding to a gap between pressure chambers C adjacent to each other in a plan view. When the diaphragm 111e vibrates in conjunction with the above deformation of the drive element 111f, the pressure in the pressure chamber C fluctuates, so that ink is discharged from the nozzle N.

The protective plate 111g is a plate-shaped member installed on the surface of the diaphragm 111e facing the Z1 direction, protects the plurality of drive elements 111f, and reinforces the mechanical strength of the diaphragm 111e. Here, the plurality of drive elements 111f are accommodated between the protective plate 111g and the diaphragm 111e. The protective plate 111g is made of, for example, a resin material.

The case 111h is a member for storing ink supplied to the plurality of pressure chambers C. The case 111h is made of, for example, a resin material. The case 111h is provided with a space R2 for each of the first row L1 and the second row L2. The space R2 is a space communicating with the above-described space R1 and functions as a reservoir R for storing ink supplied to the plurality of pressure chambers C together with the space R1. The case 111h is provided with an inlet IH for supplying ink to each reservoir R. The ink in each reservoir R is supplied to the pressure chamber C via each supply flow path Ra.

The vibration absorber 111d, also referred to as a compliance substrate, is a flexible resin film constituting the wall surface of the reservoir R, and absorbs pressure fluctuations of ink in the reservoir R. The vibration absorber 111d may be a thin plate made of metal and having flexibility. The surface of the vibration absorber 111d facing the Z1 direction is bonded to the flow path substrate 111a with an adhesive or the like.

The wiring substrate 111i is mounted on the surface of the diaphragm 111e facing the Z1 direction, and is a mounting component for electrically coupling the head chip 111, the drive circuit 112, the control module 110b, and the like. The wiring substrate 111i is a flexible wiring substrate such as a chip on film (COF), a flexible printed circuit (FPC), or a flexible flat cable (FFC). The drive circuit 112 described above is mounted on the wiring substrate 111i of the present embodiment.

1-3. Configuration of First Processing Device

FIG. 4 is a schematic diagram illustrating a configuration example of the first processing device 200 used in the ink jet system 10 according to the first embodiment. As illustrated in FIG. 4, the first processing device 200 includes a display device 210, an input device 220, a communication device 230, a storage circuit 240, and a processing circuit 250. These components are communicably coupled to each other.

The display device 210 displays various images under the control of the processing circuit 250. Here, the display device 210 includes various display panels such as a liquid crystal display panel or an organic electro-luminescence

11

(EL) display panel, for example. The display device 210 may be provided outside the first processing device 200. In addition, the display device 210 may be a component of the ink discharge device 100.

The input device 220 is a device that receives an operation from the user. For example, the input device 220 includes a pointing device such as a touch pad, a touch panel, or a mouse. Here, when the input device 220 includes the touch panel, the input device 220 may also serve as a display device 210. The input device 220 may be provided outside the first processing device 200. In addition, the input device 220 may be a component of the ink discharge device 100. In addition, the input device 220 may include an image pickup device having a charge coupled device (CCD) image sensor, a complementary MOS (CMOS) image sensor, or the like.

The communication device 230 is a circuit capable of communicating with each of the ink discharge device 100 and the server 300. For example, the communication device 230 is an interface such as a wireless or wired LAN or USB. The communication device 230 transmits the recorded data DP to the ink discharge device 100 by communicating with the ink discharge device 100. In addition, the communication device 230 transmits the output information D1 and receives the input information D2 by communicating with the server 300. That is, the communication device 230 functions as a first coupling portion 231 that is communicably coupled to the server 300. The communication device 230 may be integrated with the processing circuit 250.

The storage circuit 240 is a device that stores various programs executed by the processing circuit 250 and various data processed by the processing circuit 250. The storage circuit 240 includes, for example, a hard disk drive or a semiconductor memory. A part or all of the storage circuit 240 may be provided in a storage device or a server outside the first processing device 200.

The storage circuit 240 of the present embodiment stores a program PG1, the output information D1, the input information D2, the image data DI, and the recorded data DP. A part or all of the output information D1, the input information D2, the image data DI, and the recorded data DP may be stored in an external storage device or server of the first processing device 200. In addition, in the following, the program PG1, the output information D1, and the input information D2 may be collectively referred to as information DG.

The program PG1 is a program that enables a computer to realize various functions necessary for determining the recording condition of the print processing based on the input information D2.

The output information D1 includes first output information D1a, second output information D1b, and third output information D1c. Depending on the determination target in a determination portion 254 described later, one of the first output information D1a and the second output information D1b may be omitted, or the third output information D1c may be omitted.

The first output information D1a is information regarding the head unit 110, and in particular, information regarding the discharge characteristic of the head unit 110. The first output information D1a may be any information as long as the information can identify the discharge characteristic of the head unit 110, and is, for example, identification information such as a serial number or a product name unique to the head unit 110. The first output information D1a is not limited to the identification information, and may be, for example, measurement information obtained by measuring the discharge characteristic of the head unit 110.

12

The second output information D1b is information regarding the ink used for the head unit 110, and in particular, information regarding the viscosity of the ink. The second output information D1b may be any information as long as the information can identify the viscosity of the ink, and is, for example, identification information such as an ink product number or a product name. The second output information D1b is not limited to the identification information, and may be, for example, measurement information obtained by measuring the vibration waveform remaining after the drive element 111f is driven.

The third output information D1c is information regarding the temperature of the ink used in the head unit 110. The third output information D1c may be any information that can identify the temperature, and is, for example, information regarding the output of a temperature sensor disposed at or in the vicinity of the head unit 110. The temperature of the ink in the vicinity of the pressure chamber C may be measured by using a part of the drive element 111f, and the information regarding the measurement temperature may be used as the third output information D1c. In addition, the temperature of the ink used for the head unit 110 can be estimated to some extent based on the first output information D1a, but since the temperature of the ink is affected by the operating environment temperature of the head unit 110, information regarding the operating environment temperature may be used as the third output information D1c. In this case, for example, the temperature of the ink used for the head unit 110 is estimated based on the first output information D1a and the third output information D1c.

In addition to each information described above, information regarding other usage conditions of the head unit 110 may be added to the output information D1.

The input information D2 is information regarding the recording condition of the print processing. The input information D2 is provided from the server 300 to the first processing device 200 as described above. In the example illustrated in FIG. 4, the input information D2 includes first input information D2a, second input information D2b, and third input information D2c.

The first input information D2a is information regarding the drive timing of the drive element 111f. The second input information D2b is information regarding the scanning speed of the head unit 110. The third input information D2c is information regarding the gap between the head unit 110 and the medium. In the following, the drive timing of the drive element 111f may be simply referred to as a “drive timing”, the scanning speed of the head unit 110 may be simply referred to as a “scanning speed”, and the gap between the head unit 110 and the medium may be simply referred to as a “gap”. The details of these pieces of information will be described later with reference to FIGS. 7 to 12.

The processing circuit 250 is a device having a function of controlling each part of the first processing device 200 and a function of processing various data. The processing circuit 250 includes, for example, a processor such as a central processing unit (CPU). The processing circuit 250 may be configured to include a single processor or may be configured to include a plurality of processors. In addition, a part or all of the functions of the processing circuit 250 may be realized by hardware such as a digital signal processor (DSP), an application specific integrated circuit (ASIC), a programmable logic device (PLD), and a field programmable gate array (FPGA).

The processing circuit 250 functions as an acquisition portion 251, a first output portion 252, a first input portion

253, a determination portion 254, and a reception portion 255 by reading and executing the program PG1 from the storage circuit 240.

The acquisition portion 251 acquires the output information D1. In the present embodiment, the acquisition portion 251 acquires the first output information D1a, the second output information D1b, and the third output information D1c. For example, the acquisition portion 251 has a function of receiving the output information D1 via the input device 220, and acquires the output information D1 by using the function. The acquired output information D1 is stored in the storage circuit 240 as described above. The acquisition portion 251 may acquire the first output information D1a from the ink discharge device 100.

The first output portion 252 outputs the output information D1 via the first coupling portion 231. For example, the first output portion 252 outputs the output information D1 to the server 300 via the first coupling portion 231 using an instruction or the like by a user using the input device 220 as a trigger.

The input information D2 is input to the first input portion 253 via the first coupling portion 231. For example, the input information D2 is input from the server 300 to the first input portion 253 via the first coupling portion 231 using an instruction or the like by the user using the input device 220 as a trigger.

The determination portion 254 determines the recording condition of the print processing based on the input information D2. In addition, the determination portion 254 determines whether or not to execute the print processing of the recording condition based on the input information D2 based on the reception result of the reception portion 255. The details of the determination will be described later with reference to FIG. 6.

The reception portion 255 receives an instruction by the user as to whether or not to execute the print processing under the recording condition indicated by the input information D2. For example, the reception portion 255 receives the instruction via the input device 220.

1-4. Configuration of Server

FIG. 5 is a schematic diagram illustrating a configuration example of the server 300 used in the ink jet system 10 according to the first embodiment. As illustrated in FIG. 5, the server 300 includes a display device 310, an input device 320, a communication device 330, a storage circuit 340, and a processing circuit 350. These components are communicably coupled to each other. The storage circuit 340 is an example of a "storage portion".

The display device 310 is a device that displays various images under the control of the processing circuit 350, and is configured in the same manner as the display device 210 described above. The input device 320 is a device that receives an operation from the user, and is configured in the same manner as the input device 220 described above. The communication device 330 is a circuit capable of communicating with each first processing device 200, and is configured in the same manner as the communication device 230 described above. The communication device 330 may be integrated with the processing circuit 350.

Here, the communication device 330 receives the output information D1 and transmits the input information D2 by communicating with the first processing device 200. That is, the communication device 330 functions as a second coupling portion 331 that is communicably coupled to the first coupling portion 231. In addition, the communication device 330 transmits the output information D1 and receives the

correspondence information D4 by communicating with the third processing device 400, when necessary.

The storage circuit 340 is a device that stores various programs executed by the processing circuit 350 and various data processed by the processing circuit 350, and is configured in the same manner as the storage circuit 240 described above. The storage circuit 340 stores the program PG2, the output information D1, the input information D2, and the correspondence information D4.

10 The program PG2 is a program that enables a computer to realize various functions necessary for generating the input information D2 based on the output information D1. The correspondence information D4 is information regarding the correspondence relationship between the output information D1 and the recording condition of the print processing to be executed. The details of the correspondence information D4 will be described later with reference to FIGS. 7 to 12.

15 The processing circuit 350 is a device having a function of controlling each part of the server 300 and a function of processing various data, and is configured in the same manner as the processing circuit 250 described above. The processing circuit 350 functions as a second output portion 351, a second input portion 352, and a calculation portion 353 by reading the program PG2 from the storage circuit 340 and executing the program PG2.

20 The second output portion 351 outputs the input information D2 via the second coupling portion 331. For example, the second output portion 351 outputs the input information D2 to the first processing device 200 via the second coupling portion 331 using an instruction or the like by the user using the input device 220 as a trigger.

25 The output information D1 is input to the second input portion 352 via the second coupling portion 331. For example, the output information D1 is input from the first processing device 200 to the second input portion 352 via the second coupling portion 331 using an instruction or the like by the user using the input device 220 as a trigger.

30 The calculation portion 353 performs a calculation to generate the input information D2 based on the output information D1 and the correspondence information D4. Here, the calculation portion 353 receives input of new correspondence information D4 from the third processing device 400 depending on the collation result of the output information D1 and the correspondence information D4, and generates the input information D2 by using the new correspondence information D4 from the third processing device 400.

35 More specifically, when the output information D1 from the second input portion 352 is included in the correspondence information D4, the calculation portion 353 generates the input information D2 based on the output information D1 and the correspondence information D4. On the other hand, when the first output information D1a and the second output information D1b, which have a greater influence on the image quality than the third output information D1c, are included in the correspondence information D4, even when a part of the output information D1 from the second input portion 352 is not included in the correspondence information D4, the calculation portion 353 generates information 40 regarding the recording condition corresponding to the information closest to the output information D1 from the second input portion 352 among the output information D1 indicated by the correspondence information D4 as the input information D2. In addition, when one or both of the first output information D1a and the second output information D1b from the second input portion 352 are not included in the correspondence information D4, the calculation portion 45

353 receives the input of the new correspondence information D4 from the third processing device 400, and generates the input information D2 using the new correspondence information D4 from the third processing device 400. The correspondence information D4 stored in the storage circuit 340 is rewritten into the new correspondence information D4.

Here, the third processing device 400 uses the output information D1 from the server 300 to generate new correspondence information D4. That is, the third processing device 400 includes an update portion 410 that updates the correspondence information D4. The update portion 410 updates the correspondence information D4 by appropriately using the information input from the operator of the third processing device 400 or the administrator of the ink jet system 10 in addition to the output information D1 and the correspondence information D4. In addition, the update portion 410 causes the server 300 to transmit the updated correspondence information D4. When the third processing device 400 does not have the original correspondence information D4, the third processing device 400 may update the correspondence information D4 after receiving the input of the correspondence information D4 in addition to the output information D1 from the server 300.

1-5. Ink Jet System Processing

FIG. 6 is a flowchart illustrating the processing of the ink jet system 10 according to the first embodiment. In the ink jet system 10, first, as illustrated in FIG. 6, the first processing device 200 acquires the output information D1 in step S101.

Specifically, in step S101, for example, the acquisition portion 251 acquires the output information D1 by receiving the output information D1 via the input device 220. In step S101, the acquisition order of the first output information D1a, the second output information D1b, and the third output information D1c is not particularly limited and is optional. In addition, for example, the acquisition portion 251 may display an image for a graphical user interface (GUI) for inputting information necessary for acquiring the output information D1 on the display device 210 and appropriately receive information necessary for acquiring the output information D1 from the user using the image.

In step S102, the first processing device 200 outputs the output information D1 to the server 300.

Specifically, in step S102, the first output portion 252 outputs the output information D1 via the first coupling portion 231 with the acquisition of the output information D1 as a trigger. The timing at which the output information D1 is output to the first coupling portion 231 is not limited to the time when the output information D1 is acquired. For example, when the input using the GUI image described above is received, the first output portion 252 may transmit the authentication information such as the user's account information and password to the server 300, when the server 300 succeeds in the authentication using the authentication information, may send the output permission information from the server 300 to the first processing device 200, and when the first processing device 200 receives the output permission information, may output the output information D1 to the server 300.

Next, in step S103, the server 300 inputs the output information D1. In step S104, the server 300 generates the input information D2 based on the output information D1. More specifically, in step S104, the calculation portion 353 performs a calculation to generate the input information D2 based on the output information D1 and the correspondence information D4. The server 300 may inquire about the

output information D1 with the predetermined inquiry information, and may cancel the processing after step S104 according to the inquiry result. In addition, the input information D2 indicating that information on the recording condition of the print processing is not provided may be output to the second output portion 351 according to the inquiry result.

Thereafter, in step S105, the server 300 outputs the input information D2 to the first processing device 200.

10 Next, in step S106, the first processing device 200 inputs the input information D2. Specifically, in step S106, the input information D2 from the server 300 is input to the first input portion 253 via the first coupling portion 231. The first input portion 253 notifies the user whether or not to input the input information D2 from the server 300 by using the display device 210 or the like, and the input information D2 from the server 300 may be input only when the user inputs an instruction for permitting input by the input device 220 or the like.

15 20 In step S107, it is determined whether or not the first processing device 200 executes the print processing under the recording condition indicated by the input information D2. Specifically, the display device 210 displays an image for receiving an instruction as to whether or not the reception portion 255 executes the print processing under the recording condition indicated by the input information D2. The reception portion 255 receives the instruction as to whether or not to execute the print processing under the recording condition indicated by the input information D2 via the input device 220.

25 30 When an instruction to execute the print processing under the recording condition indicated by the input information D2 is received, the first processing device 200 determines the recording condition of the print processing based on the input information D2 in step S108.

35 On the other hand, when an instruction not to execute the print processing under the recording condition indicated by the input information D2 is received, in step S109, the first processing device 200 determines to execute the print processing under another recording condition input by the user.

40 The determination portion 254 may determine the recording condition to be actually used after fine-tuning the recording condition indicated by the input information D2 by user input using the input device 220.

45 50 When the recording condition is determined by the determination portion 254, the recording condition is set. Specifically, the drive timing indicated by the first input information D2a, the scanning speed indicated by the second input information D2b, and the gap indicated by the third input information D2c are set. The drive timing indicated by the first input information D2a is set, for example, by shifting a supply timing of the drive signal Com to the drive element 111f. The supply timing may be changed, for example, by changing the operation timing of the drive circuit 112, or by performing image processing on the recorded data DP. Each of the setting of the scanning speed indicated by the second input information D2b and the setting of the gap indicated by the third input information D2c is performed by, for example, adjusting the control signal Sk. When the scanning speed is changed, the ink discharge timing is adjusted so that a pitch between the pixels at the ink landing position on the medium is within a reference range.

1-6. Processing in Calculation Portion

55 60 In the calculation of the calculation portion 353, at least one of the first input information D2a, the second input information D2b, and the third input information D2c is

adjusted based on the correspondence information D4 so that the recording condition of the print processing is optimized. Here, in the calculation, it is preferable that any one of the first input information D2a, the second input information D2b, and the third input information D2c is adjusted from the viewpoint of ease of adjustment. From the viewpoint of preferably improving the image quality, it is more preferable that the first input information D2a is adjusted.

The landing position of the ink discharged from the head differs depending on the head, ink, and temperature. Therefore, depending on the printer manufacturer or the printer user, a landing position adjustment regarding a landing position not expected by the head manufacturer may be performed, and the image quality may not be sufficiently obtained. For example, a case where a head manufacturer provides the landing position adjustment (drive timing, scanning speed, gap, and the like described later) designed to be an optimum landing position in the combination of the premises on the premise of a combination of a certain head, ink, and temperature is considered as an example. For the sake of simplicity, the following description describes the case where the printer manufacturer and the printer user match, that is, the user who purchased the head manufacturer manufactures the printer by himself or herself and further uses the printer, but it is basically the same even when the printer manufacturer and the printer user are different.

In particular, when the head manufacturer and the printer manufacturer are different, the ink and temperature recommended for use are determined by the printer manufacturer. At that time, a printer manufacturer who does not have much knowledge may not be able to determine what type of landing position adjustment is optimal. It suffices when the head manufacturer can provide the information on the landing position adjustment in advance, but as described above, the ink and temperature recommended for use differ depending on the printer manufacturer, and the information on the optimum landing position differs depending on the ink and temperature. Therefore, in the past, even the head manufacturer could not determine what type of landing position adjustment is required to be performed.

For example, it is assumed that the printer manufacturer uses an ink having a viscosity higher than the ink assumed by the head manufacturer. When the viscosity of the ink is high, the discharge speed of the ink from the head is reduced. When the discharge speed is reduced, the landing position is shifted accordingly. In this manner, even when the information on the optimum landing position adjustment is used for the ink that the head manufacturer has assumed in advance, the actual landing position is shifted because the viscosity of the ink is high.

In addition, as another example, it is assumed that the printer manufacturer sets the temperature at which the printer operates to be lower than the temperature assumed by the head manufacturer. Normally, the lower the temperature, the higher the viscosity. Therefore, when the operating temperature of the printer is low, the viscosity increases, and there is a possibility that the landing position is shifted in the same manner as described above. In this manner, even when the information on the optimum landing position adjustment is used at the temperature assumed by the head manufacturer in advance, the actual landing position is shifted because the temperature is low.

As still another example, the printer manufacturer may have a plurality of types of heads manufactured by the head manufacturer and having different discharge characteristics from each other. In that case, even when the printer man-

facturer uses a certain head of the plurality of types of heads and uses the information on the optimum landing position adjustment for another head B whose discharge speed is lower than that of a certain head A, the actual landing position is shifted.

As described above, the information on the optimum landing position adjustment differs depending on the combination of the head, ink, and temperature adopted by the printer manufacturer. It may be difficult for printer manufacturers to find the optimum information. On the other hand, even when the head manufacturer tries to provide the information on the landing position adjustment according to the head, ink, and temperature in advance, since the information on the landing position adjustment can be optionally determined by the printer manufacturer, it is difficult to recognize the information on the landing position adjustment at the time of manufacturing and selling the head. Therefore, it was difficult for the head manufacturer to provide appropriate information on the landing position adjustment.

In view of this point, in the present embodiment, as described above, the first processing device 200_1 in the hand of the printer manufacturer and the server 300 provided, maintained, and managed by the head manufacturer can be coupled via the communication network NW, and the head, ink, and temperature used by the printer manufacturer can be directly input to the server 300 of the head manufacturer. As a result, the appropriate information on the landing position adjustment according to the head, ink, and temperature can be easily provided from the head manufacturer to the printer manufacturer, and the burden on the printer manufacturer can be reduced.

Specifically, in the present embodiment, the first processing device 200 outputs the first output information D1a regarding the head unit 110, the second output information D1b regarding the ink, and the third output information D1c regarding the temperature toward the server 300. The server 300 uses the correspondence information D4 to calculate the input information D2 corresponding to the input first output information D1a, the second output information D1b, and the third output information D1c (including the first input information D2a, the second input information D2b, and the third input information D2c) and outputs the result to the first processing device 200.

45 1-6a. Generation of First Input Information D2a

Example 1

As Example 1 of the first embodiment, a case where the drive timing is varied according to the first output information D1a, the second output information D1b, and the third output information D1c will be described below.

FIG. 7 is a table for describing information D4a illustrating a correspondence relationship between the output information D1 and the first input information D2a of information included in the correspondence information D4. The information D4a is used when the first input information D2a is generated based on the output information D1 in the above-described step S104. In FIG. 7, the correspondence relationship between the first output information D1a, the second output information D1b, the third output information D1c, and the first input information D2a is exemplified. In FIG. 7, for convenience of description, the information D4a is illustrated in a simplified manner, and in reality, the information D4a is different from the example illustrated in FIG. 7 depending on the situation of the assumed printer manufacturer and the like.

In FIG. 7, each of “high discharge performance” and “low discharge performance” in the first column from the left is the discharge characteristic indicated by the first output information D1a, and it indicates that “high discharge performance” has a higher discharge characteristic than “low discharge performance”. That is, when the head unit 110 indicated by the first output information D1a is a head unit having high discharge performance, in FIG. 7, it means that the “first output information D1a” uses any one of the first input information D2a corresponding to the “high discharge performance”. In addition, when the head unit 110 indicated by the first output information D1a is a head unit having a low discharge performance, in FIG. 7, it means that the “first output information D1a” uses any one of the first input information D2a corresponding to the “low discharge performance”. Of the two discharge characteristics that are different from each other, the discharge characteristic is higher when the discharge speed of the ink from the nozzle is faster than when the discharge speed is slow. The discharge speed is, for example, the initial speed and the average speed at a predetermined distance from the nozzle. In addition, the discharge performance may not be classified into two stages of “high discharge performance” and “low discharge performance”, and may be classified into three or more stages in more detail. Here, “low discharge performance” is an example of “first discharge characteristic”, and “low discharge characteristic” is an example of “second discharge characteristic”. Of the two discharge characteristics that are different from each other, the discharge characteristic is higher when the maximum discharge amount per pixel from the nozzle is higher than when the maximum discharge amount is low.

In FIG. 7, each of "high viscosity" and "low viscosity" in the second column from the left is the viscosity indicated by the second output information D1b, and "high viscosity" indicates a higher viscosity than "low viscosity". Here, "low viscosity" is an example of a "first viscosity", and "high viscosity" is an example of a "second viscosity". In addition, specifically, whether the viscosity is high or low may be determined depending on whether the viscosity is equal to or more than or less than a predetermined threshold value. In addition, the viscosity may not be classified into two stages of "high viscosity" and "low viscosity", and may be classified into three or more stages in more detail.

In FIG. 7, each of “high temperature” and “low temperature” in the third column from the left is the temperature indicated by the third output information D1c, and indicates that “high temperature” is higher temperature than “low temperature”. Here, “low temperature” is an example of a “first temperature”, and “high temperature” is an example of a “second temperature”. In addition, specifically, whether the temperature is high or low may be determined by whether the temperature is equal to or more than or lower than a predetermined threshold value. In addition, the temperature may not be classified into two stages of “high temperature” and “low temperature”, and may be classified into three or more stages in more detail.

In FIG. 7, each numerical value of “-3” to “+3” in the fourth column from the left is the drive timing [0.1 seconds] indicated by the first input information D2a. In the example illustrated in FIG. 7, the reference timing is set to “0”, “+” indicates that it is later than the reference timing, and “-” indicates that it is earlier than the reference timing. For example, “+3” indicates that the timing is 0.3 seconds later than the reference timing.

In step S104 described above, the calculation portion 353 of the server 300 generates the first input information D2a

5 by selecting one of “-3” to “+3” as the drive timing of the drive element **111f** using the information **D4a** as illustrated in FIG. 7 based on the first output information **D1a**, the second output information **D1b**, and the third output information **D1c** from the second input portion **352**.

Specifically, when the discharge characteristic indicated by the first output information D1a is “high discharge performance”, the viscosity indicated by the second output information D1b is “low viscosity”, and the temperature indicated by the third output information D1c is “high temperature”, “+3” is selected as the first input information D2a. When the discharge characteristic indicated by the first output information D1a is “high discharge performance”, the viscosity indicated by the second output information D1b is “low viscosity”, and the temperature indicated by the third output information D1c is “low temperature”, “+1” is selected as the first input information D2a. When the discharge characteristic indicated by the first output information D1a is “high discharge performance”, the viscosity indicated by the second output information D1b is “high viscosity”, and the temperature indicated by the third output information D1c is “low temperature”, “+2” is selected as the first input information D2a. When the discharge characteristic indicated by the first output information D1a is “high discharge performance”, the viscosity indicated by the second output information D1b is “high viscosity”, and the temperature indicated by the third output information D1c is “low temperature”, “±0” is selected as the first input information D2a. When the discharge characteristic indicated by the first output information D1a is “low discharge performance”, the viscosity indicated by the second output information D1b is “low viscosity”, and the temperature indicated by the third output information D1c is “high temperature”, “±0” is selected as the first input information D2a. When the discharge characteristic indicated by the first output information D1a is “low discharge performance”, the viscosity indicated by the second output information D1b is “low viscosity”, and the temperature indicated by the third output information D1c is “low temperature”, “-2” is selected as the first input information D2a. When the discharge characteristic indicated by the first output information D1a is “low discharge performance”, the viscosity indicated by the second output information D1b is “high viscosity”, and the temperature indicated by the third output information D1c is “high temperature”, “-1” is selected as the first input information D2a. When the discharge characteristic indicated by the first output information D1a is “low discharge performance”, the viscosity indicated by the second output information D1b is “high viscosity”, and the temperature indicated by the third output information D1c is “low temperature”, “-3” is selected as the first input information D2a.

Here, among the drive timings when the discharge characteristic indicated by the first output information D1a is “low discharge characteristic”, a drive timing earlier than the drive timing when the discharge characteristic indicated by the first output information D1a is “high discharge characteristic” is an example of a “first drive timing”. In addition, among the drive timings when the discharge characteristic indicated by the first output information D1a is “high discharge characteristic”, a drive timing later than the drive timing when the discharge characteristic indicated by the first output information D1a is “low discharge characteristic” is an example of a “second drive timing”.

65 In addition, among the drive timings when the viscosity indicated by the second output information D1b is "low viscosity", a drive timing later than the drive timing when

the viscosity indicated by the second output information D1b is “high viscosity” is an example of a “third drive timing”. In addition, among the drive timings when the viscosity indicated by the second output information D1b is “high viscosity”, a drive timing earlier than the drive timing when the viscosity indicated by the second output information D1b is “low viscosity” is an example of a “fourth drive timing”.

Furthermore, among the drive timings when the temperature indicated by the third output information D1c is “low temperature”, a drive timing earlier than the drive timing when the temperature indicated by the third output information D1c is “high temperature” is an example of a “fifth drive timing”. In addition, among the drive timings when the temperature indicated by the third output information D1c is “high temperature”, a drive timing later than the drive timing when the temperature indicated by the third output information D1c is “low temperature” is an example of a “sixth drive timing”.

FIG. 8 is a diagram for describing a drive timing t based on the first input information D2a. In FIG. 8, regarding the landing position of the ink from the head unit 110 to the medium M, an ideal position P0, a position P1 shifted from the ideal position P0, and a position P1a corrected based on the first input information D2a are illustrated.

Specifically, as illustrated in the upper part of FIG. 8, the drive timing t is set to a reference value of 0, and the discharge speed of the ink from the head unit 110 when the ink discharged from the head unit 110 lands at the ideal position P0 on the medium M is a speed VD0. Here, when the scanning speed of the head unit 110 is set to a speed VSO, the ink lands on the medium M at the intersection of the composite vector VC0 of the speed VSO and the speed VD0 or an extension line thereof and the medium M. The intersection is the ideal position P0. A gap between the head unit 110 and the medium M is a gap Gap0.

As illustrated in the middle part of FIG. 8, when the discharge speed of the ink from the head unit 110 is a speed VD1 different from the speed VD0, and other conditions are the same as the state of the upper part in FIG. 8, the ink from the head unit 110 lands at the position P1 shifted from the ideal position P0 on the medium M by a distance $\Delta L1$. In the example illustrated in FIG. 8, the speed VD1 is slower than the speed VD0. Therefore, the position P1 is a position farther from the head unit 110 from the ideal position P0.

Therefore, when the discharge speed of the ink from the head unit 110 is a speed VD1 different from the speed VD0, the calculation portion 353 generates the first input information D2a in which the ink discharge timing from the head unit 110 is adjusted so that the ink from the head unit 110 lands on the ideal position P0 on the medium M. When the head unit 110 uses a plurality of types of ink, the adjustment may be performed for each type of ink.

In the example illustrated in FIG. 8, the ink discharge timing from the head unit 110 is adjusted to be earlier. That is, as illustrated in the lower part of FIG. 8, the drive timing t is set so that the position P1a, which is the intersection of the composite vector VC1 of the speed VSO and the speed VD1 or an extension line thereof and the medium M, is the ideal position P0. In FIG. 8, the case where $t=-3$ is illustrated. The first input information D2a indicating such a drive timing t is generated by the calculation portion 353.

1-6b. Generation of Second Input Information D2b

Example 2

As Example 2 of the first embodiment, a case where the scanning speed is varied according to the first output infor-

mation D1a, the second output information D1b, and the third output information D1c will be described below.

FIG. 9 is a table for describing information D4b illustrating a correspondence relationship between the output information D1 and the second input information D2b of the information included in the correspondence information D4. The information D4b is used when the second input information D2b is generated based on the output information D1 in the above-described step S104. In FIG. 9, the correspondence relationship between the first output information D1a, the second output information D1b, the third output information D1c, and the second input information D2b is exemplified. In FIG. 9, for convenience of description, the information D4b is illustrated in a simplified manner, and in reality, the information D4b is different from the example illustrated in FIG. 9 depending on the situation of the assumed printer manufacturer and the like.

In FIG. 9, each numerical value of “35” to “50” in the fourth column from the left is the scanning speed [inch/sec] indicated by the second input information D2b.

In step S104 described above, the calculation portion 353 of the server 300 generates the second input information D2b by selecting one of “35” to “50” as the scanning speed of the head unit 110 using the information D4b as illustrated in FIG. 9 based on the first output information D1a, the second output information D1b, and the third output information D1c from the second input portion 352.

Specifically, when the discharge characteristic indicated by the first output information D1a is “high discharge performance”, the viscosity indicated by the second output information D1b is “low viscosity”, and the temperature indicated by the third output information D1c is “high temperature”, “50” is selected as the second input information D2b. When the discharge characteristic indicated by the first output information D1a is “high discharge performance”, the viscosity indicated by the second output information D1b is “low viscosity”, and the temperature indicated by the third output information D1c is “low temperature”, “45” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “45” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “40” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “40” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “35” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “35” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “30” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “30” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “25” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “25” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “20” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “20” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “15” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “15” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “10” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “10” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “5” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “5” is selected as the second input information D2b. When the discharge characteristic indicated by the first output information D1a is “high discharge performance”, the viscosity indicated by the second output information D1b is “high viscosity”, and the temperature indicated by the third output information D1c is “low temperature”, “0” is selected as the second input information D2b. When the discharge characteristic indicated by the first output information D1a is “high discharge performance”, the viscosity indicated by the second output information D1b is “high viscosity”, and the temperature indicated by the third output information D1c is “high temperature”, “0” is selected as the second input information D2b.

cated by the third output information D1c is “high temperature”, “40” is selected as the second input information D2b. When the discharge characteristic indicated by the first output information D1a is “low discharge performance”, the viscosity indicated by the second output information D1b is “high viscosity”, and the temperature indicated by the third output information D1c is “low temperature”, “35” is selected as the second input information D2b.

Here, among the scanning speeds when the discharge characteristic indicated by the first output information D1a is “low discharge characteristic”, a scanning speed slower than the scanning speed when the discharge characteristic indicated by the first output information D1a is “high discharge characteristic” is an example of a “first scanning speed”. In addition, among the scanning speeds when the discharge characteristic indicated by the first output information D1a is “high discharge characteristic”, a scanning speed faster than the scanning speed when the discharge characteristic indicated by the first output information D1a is “low discharge characteristic” is an example of a “second scanning speed”.

In addition, among the scanning speeds when the viscosity indicated by the second output information D1b is “low viscosity”, a scanning speed faster than the scanning speed when the viscosity indicated by the second output information D1b is “high viscosity” is an example of a “third scanning speed”. In addition, among the scanning speeds when the viscosity indicated by the second output information D1b is “high viscosity”, a scanning speed slower than the scanning speed when the viscosity indicated by the second output information D1b is “low viscosity” is an example of a “fourth scanning speed”.

Furthermore, among the scanning speeds when the temperature indicated by the third output information D1c is “low temperature”, a scanning speed slower than the scanning speed when the temperature indicated by the third output information D1c is “high temperature” is an example of a “fifth scanning speed”. In addition, among the scanning speeds when the temperature indicated by the third output information D1c is “high temperature”, a scanning speed faster than the scanning speed when the temperature indicated by the third output information D1c is “low temperature” is an example of a “sixth scanning speed”.

FIG. 10 is a diagram for describing the scanning speed based on the second input information D2b. In FIG. 10, regarding the landing position of the ink from the head unit 110 to the medium M, an ideal position P0, a position P2 shifted from the ideal position P0, and a position P2a corrected based on the second input information D2b are illustrated.

Specifically, in the upper part of FIG. 10, the drive timing t is set to a reference value of 0, and the discharge speed of the ink from the head unit 110 when the ink discharged from the head unit 110 lands at the ideal position P0 on the medium M is a speed VD0, as in the upper part of FIG. 8 described above.

As illustrated in the middle part of FIG. 10, when the discharge speed of the ink from the head unit 110 is a speed VD2 different from the speed VD0, and other conditions are the same as the state of the upper part in FIG. 10, the ink from the head unit 110 lands at a position P2 shifted from the ideal position P0 on the medium M by a distance $\Delta L2$. In the example illustrated in FIG. 10, the speed VD2 is faster than the speed VD0. Therefore, the position P2 is a position closer to the head unit 110 than the ideal position P0.

Therefore, when the discharge speed of the ink from the head unit 110 is a speed VD2 different from the speed VD0, the calculation portion 353 generates the second input information D2b in which the scanning speed of the head unit 110 is adjusted so that the ink from the head unit 110 lands on the ideal position P0 on the medium M.

In the example illustrated in FIG. 10, the scanning speed of the head unit 110 is adjusted to increase. That is, as is illustrated in the lower part of FIG. 10, the speed VD2 is set so that the position P2a, which is the intersection of the composite vector VC2 of the speed VSO and the speed VD2 or an extension line thereof and the medium M, is the ideal position P0. The second input information D2b indicating such a scanning speed is generated by the calculation portion 353.

1-6c. Generation of Third Input Information D2c

Example 3

As Example 3 of the first embodiment, a case where the gap between the head unit 110 and the medium M is varied according to the first output information D1a, the second output information D1b, and the third output information D1c will be described below.

FIG. 11 is a table for describing information D4c illustrating a correspondence relationship between the output information D1 and the third input information D2c of the information included in the correspondence information D4. The information D4c is used when the third input information D2c is generated based on the output information D1 in the above-described step S104. In FIG. 11, the correspondence relationship between the first output information D1a, the second output information D1b, the third output information D1c, and the third input information D2c is exemplified. In FIG. 11, for convenience of description, the information D4c is illustrated in a simplified manner, and in reality, the information D4c is different from the example illustrated in FIG. 11 depending on the situation of the assumed printer manufacturer and the like.

In FIG. 11, each numerical value of “19” to “30” in the fourth column from the left is the gap [mm] indicated by the third input information D2c.

In step S104 described above, the calculation portion 353 of the server 300 generates the third input information D2c by selecting one of “19” to “30” as the gap between the head unit 110 and the medium M using the information D4c as illustrated in FIG. 11 based on the first output information D1a, the second output information D1b, and the third output information D1c from the second input portion 352.

Specifically, when the discharge characteristic indicated by the first output information D1a is “high discharge performance”, the viscosity indicated by the second output information D1b is “low viscosity”, and the temperature indicated by the third output information D1c is “high temperature”, “30” is selected as the third input information D2c. When the discharge characteristic indicated by the first output information D1a is “high discharge performance”, the viscosity indicated by the second output information D1b is “high viscosity”, and the temperature indicated by the third output information D1c is “high temperature”, “29” is selected as the third input information D2c. When the discharge characteristic indicated by the first output information D1a is “high discharge performance”, the viscosity indicated by the second output information D1b is “high viscosity”, and the temperature indicated by the third output information D1c is “low temperature”, “27” is selected as the third input information D2c. When the discharge characteristic indicated by the first output information D1a is “high discharge performance”, the viscosity indicated by the second output information D1b is “low viscosity”, and the temperature indicated by the third output information D1c is “low temperature”, “25” is selected as the third input information D2c.

acteristic indicated by the first output information D1a is “high discharge performance”, the viscosity indicated by the second output information D1b is “high viscosity”, and the temperature indicated by the third output information D1c is “low temperature”, “24” is selected as the third input information D2c. When the discharge characteristic indicated by the first output information D1a is “low discharge performance”, the viscosity indicated by the second output information D1b is “low viscosity”, and the temperature indicated by the third output information D1c is “high temperature”, “25” is selected as the third input information D2c. When the discharge characteristic indicated by the first output information D1a is “low discharge performance”, the viscosity indicated by the second output information D1b is “low viscosity”, and the temperature indicated by the third output information D1c is “low temperature”, “22” is selected as the third input information D2c. When the discharge characteristic indicated by the first output information D1a is “low discharge performance”, the viscosity indicated by the second output information D1b is “high viscosity”, and the temperature indicated by the third output information D1c is “high temperature”, “24” is selected as the third input information D2c. When the discharge characteristic indicated by the first output information D1a is “low discharge performance”, the viscosity indicated by the second output information D1b is “high viscosity”, and the temperature indicated by the third output information D1c is “low temperature”, “22” is selected as the third input information D2c. When the discharge characteristic indicated by the first output information D1a is “low discharge performance”, the viscosity indicated by the second output information D1b is “low viscosity”, and the temperature indicated by the third output information D1c is “low temperature”, “25” is selected as the third input information D2c. When the discharge characteristic indicated by the first output information D1a is “low discharge performance”, the viscosity indicated by the second output information D1b is “high viscosity”, and the temperature indicated by the third output information D1c is “high temperature”, “24” is selected as the third input information D2c. When the discharge characteristic indicated by the first output information D1a is “low discharge performance”, the viscosity indicated by the second output information D1b is “high viscosity”, and the temperature indicated by the third output information D1c is “low temperature”, “22” is selected as the third input information D2c. When the discharge characteristic indicated by the first output information D1a is “low discharge performance”, the viscosity indicated by the second output information D1b is “low viscosity”, and the temperature indicated by the third output information D1c is “low temperature”, “19” is selected as the third input information D2c.

Here, among the gaps when the discharge characteristic indicated by the first output information D1a is “low discharge characteristic”, a gap shorter than the gap when the discharge characteristic indicated by the first output information D1a is “high discharge characteristic” is an example of a “first gap”. In addition, among the gaps when the discharge characteristic indicated by the first output information D1a is “high discharge characteristic”, a gap longer than the gap when the discharge characteristic indicated by the first output information D1a is “low discharge characteristic” is an example of a “second gap”.

In addition, among the gaps when the viscosity indicated by the second output information D1b is “low viscosity”, a gap longer than the gap when the viscosity indicated by the second output information D1b is “high viscosity” is an example of a “third gap”. In addition, among the gaps when the viscosity indicated by the second output information D1b is “high viscosity”, a gap shorter than the gap when the viscosity indicated by the second output information D1b is “low viscosity” is an example of a “fourth gap”.

Furthermore, among the gaps when the temperature indicated by the third output information D1c is “low temperature”, a gap shorter than the gap when the temperature indicated by the third output information D1c is “high temperature” is an example of a “fifth gap”. In addition, among the gaps when the temperature indicated by the third output information D1c is “high temperature”, a gap longer than the gap when the temperature indicated by the third output information D1c is “low temperature” is an example of a “sixth gap”.

FIG. 12 is a diagram for describing a gap based on the third input information D2c. In FIG. 12, regarding the landing position of the ink from the head unit 110 to the medium M, an ideal position P0, a position P3 shifted from the ideal position P0, and a position P3a corrected based on the third input information D2c are illustrated.

Specifically, in the upper part of FIG. 12, the drive timing t is set to a reference value of 0, and the discharge speed of

the ink from the head unit 110 when the ink discharged from the head unit 110 lands at the ideal position P0 on the medium M is a speed VD0, as in the upper part of FIG. 8 described above.

As illustrated in the middle part of FIG. 12, when the discharge speed of the ink from the head unit 110 is a speed VD3 different from the speed VD0, and other conditions are the same as the state of the upper part in FIG. 12, the ink from the head unit 110 lands at a position P3 shifted from the ideal position P0 on the medium M by a distance ΔL3. In the example illustrated in FIG. 12, the speed VD3 is faster than the speed VD0. Therefore, the position P3 is a position closer to the head unit 110 than the ideal position P0.

Therefore, when the discharge speed of the ink from the head unit 110 is a speed VD3 different from the speed VD0, the calculation portion 353 generates the third input information D2c in which the gap between the head unit 110 and the medium M is adjusted so that the ink from the head unit 110 lands on the ideal position P0 on the medium M.

In the example illustrated in FIG. 12, the gap between the head unit 110 and the medium M is adjusted to be long. That is, as illustrated in the lower part of FIG. 12, the gap between the head unit 110 and the medium M is set to the gap Gap1 so that the position P3a, which is the intersection of the composite vector VC3 of the speed VSO and the speed VD3 or an extension line thereof and the medium M, is the ideal position P0. The third input information D2c indicating such a gap Gap1 is generated by the calculation portion 353.

1-7. Summary of First Embodiment

As described above, the ink jet system 10 includes the head unit 110, the acquisition portion 251, the first output portion 252, the first input portion 253, and the determination portion 254. The head unit 110 includes the nozzle N for discharging ink, the pressure chamber C communicating with the nozzle N, and the drive element 111f for applying pressure fluctuation to the ink in the pressure chamber C by supplying the drive pulse PD. The acquisition portion 251 acquires the output information D1 including one or both of the first output information D1a regarding the head unit 110 and the second output information D1b regarding the ink used for the head unit 110. The first coupling portion 231 is communicably network-coupled to the server 300. The first output portion 252 outputs the output information D1 toward the server 300 via the first coupling portion 231. The input information D2 is input to the first input portion 253 from the server 300 via the first coupling portion 231. The determination portion 254 determines the recording condition of the print processing based on the input information D2. Here, the recording condition includes at least one of the drive timing of the drive element 111f, the scanning speed of the head unit 110, and the gap between the head unit 110 and the medium.

In the above ink jet system 10, since the first output portion 252 outputs the output information D1 toward the server 300 via the first coupling portion 231, the output information D1 can be provided to the head manufacturer. Therefore, by utilizing the knowledge of the head manufacturer in addition to the output information D1, the input information D2 can be efficiently obtained as the information necessary for determining the recording condition of the print processing. Since the determination portion 254 determines the recording condition of the print processing based on the input information D2 input from the server 300 to the first input portion 253 via the first coupling portion 231, the recording condition of the print processing can be determined while reducing the burden on the printer manufacturer.

In the present embodiment, the output information D1 includes the first output information D1a which is information regarding the discharge characteristic of the head unit 110, the second output information D1b which is information regarding the viscosity of the ink, and the third output information D1c regarding the temperature of the ink used for the head unit 110. The output information D1 may include one or both of the first output information D1a and the second output information D1b, and may not include the third output information D1c.

In the present embodiment, in each of Examples 1 to 3, although the case where one of the drive timing, scanning speed, and gap is varied according to the first output information D1a, the second output information D1b, and the third output information D1c is described, a plurality of Examples 1 to 3 may be combined. For example, the two combinations of the drive timing and the scanning speed may be varied depending on the first output information D1a, the second output information D1b, and the third output information D1c. In addition, for example, the three combinations of drive timing, scanning speed, and gap may be varied depending on the first output information D1a, the second output information D1b, and the third output information D1c.

As described above, when the determination portion 254 determines the drive timing of the drive element 111f as a recording condition for the print processing based on the input information D2, in a case in which the drive timing when the discharge characteristic indicated by the first output information D1a is the first discharge characteristic is set as the first drive timing, the drive timing when the discharge characteristic indicated by the first output information D1a is the second discharge characteristic higher than the first discharge characteristic is the second drive timing later than the first drive timing. Therefore, the landing position on the medium M from the head unit 110 can be brought closer to the ideal position.

In addition, as described above, when the determination portion 254 determines the drive timing of the drive element 111f as the recording condition of the print processing based on the input information D2, in a case in which the drive timing when the viscosity indicated by the second output information D1b is the first viscosity is set as the third drive timing, the drive timing when the viscosity indicated by the second output information D1b is the second viscosity higher than the first viscosity is the fourth drive timing earlier than the third drive timing. Therefore, the landing position on the medium M from the head unit 110 can be brought closer to the ideal position.

Furthermore, as described above, when the determination portion 254 determines the drive timing of the drive element 111f as the recording condition of the print processing based on the input information D2, in a case in which the drive timing when the temperature indicated by the third output information D1c is the first temperature is set as the fifth drive timing, the drive timing when the temperature indicated by the third output information D1c is the second temperature higher than the first temperature is the sixth drive timing later than the fifth drive timing. Therefore, the landing position on the medium M from the head unit 110 can be brought closer to the ideal position.

As described above, when the determination portion 254 determines the scanning speed of the head unit 110 as the recording condition of the print processing based on the input information D2, in a case in which the scanning speed when the discharge characteristic indicated by the first output information D1a is the first discharge characteristic is

set as the first scanning speed, the scanning speed when the discharge characteristic indicated by the first output information D1a is the second discharge characteristic higher than the first discharge characteristic is the second scanning speed faster than the first scanning speed. Therefore, the landing position on the medium M from the head unit 110 can be brought closer to the ideal position.

In addition, as described above, when the determination portion 254 determines the scanning speed of the head unit 110 as the recording condition of the print processing based on the input information D2, in a case in which the scanning speed when the viscosity indicated by the second output information D1b is the first viscosity is set as the third scanning speed, the scanning speed when the viscosity indicated by the second output information D1b is the second viscosity higher than the first viscosity is the fourth scanning speed faster than the third scanning speed. Therefore, the landing position on the medium M from the head unit 110 can be brought closer to the ideal position.

Furthermore, as described above, when the determination portion 254 determines the scanning speed of the head unit 110 as the recording condition of the print processing based on the input information D2, in a case in which the scanning speed when the temperature indicated by the third output information D1c is the first temperature is set as the fifth scanning speed, the scanning speed when the temperature indicated by the third output information D1c is the second temperature higher than the first temperature is the sixth scanning speed faster than the fifth scanning speed. Therefore, the landing position on the medium M from the head unit 110 can be brought closer to the ideal position.

As described above, when the determination portion 254 determines the gap between the head unit 110 and the medium as the recording condition for print processing based on the input information D2, in a case in which the gap when the discharge characteristic indicated by the first output information D1a is the first discharge characteristic is set as the first gap, the gap when the discharge characteristic indicated by the first output information D1a is the second discharge characteristic higher than the first discharge characteristic is the second gap longer than the first gap. Therefore, the landing position on the medium M from the head unit 110 can be brought closer to the ideal position.

In addition, as described above, when the determination portion 254 determines the gap between the head unit 110 and the medium as the recording condition of the print processing based on the input information D2, in a case in which the gap when the viscosity indicated by the second output information D1b is the first viscosity is set as the third gap, the gap when the viscosity indicated by the second output information D1b is the second viscosity higher than the first viscosity is the fourth gap shorter than the third gap. Therefore, the landing position on the medium M from the head unit 110 can be brought closer to the ideal position.

Furthermore, as described above, when the determination portion 254 determines the gap between the head unit 110 and the medium as the recording condition of the print processing based on the input information D2, in a case in which the gap when the temperature indicated by the third output information D1c is the first temperature is set as the fifth gap, the gap when the temperature indicated by the third output information D1c is the second temperature higher than the first temperature is the sixth gap longer than the fifth gap. Therefore, the landing position on the medium M from the head unit 110 can be brought closer to the ideal position.

As described above, the ink jet system 10 further includes a reception portion 255 that receives an instruction by the

user as to whether or not to execute the print processing under the recording condition indicated by input information D2. When the reception portion 255 receives an instruction to execute the print processing under the recording condition indicated by the input information D2, the determination portion 254 determines to execute the print processing under the recording condition indicated by the input information D2. On the other hand, when the reception portion 255 receives an instruction not to execute the print processing under the recording condition indicated by the input information D2, the determination portion 254 determines to execute print processing under another recording condition input by the user. As described above, by making the determination of the determination portion 254 based on the instruction received by the reception portion 255, the convenience of the printer manufacturer can be enhanced.

In addition, as described above, the ink jet system 10 includes the ink discharge device 100, the first processing device 200, and the server 300. The ink discharge device 100 is provided with the head unit 110. The first processing device 200 is coupled to the ink discharge device 100 and provided with the display device 210 which is an example of a "display portion" that displays information regarding the ink discharge device 100. Therefore, printing based on the recorded data DP from the first processing device 200 can be performed by the ink discharge device 100. In addition, various information can be communicated between the ink discharge device 100 and the first processing device 200. Furthermore, various information necessary for the user of the ink discharge device 100 can be notified via the display device 210.

Here, as described above, the server 300 includes the storage circuit 340, which is an example of a "storage portion", and the calculation portion 353. The storage circuit 340 stores in advance the correspondence information D4 regarding the correspondence relationship between the output information D1 and the recording condition of the print processing to be executed. The calculation portion 353 performs a calculation to generate the input information D2 based on the output information D1 and the correspondence information D4. In such a configuration in which the input information D2 is generated using the correspondence information D4, the input information D2 can be rapidly generated.

2. Second Embodiment

Hereinafter, the second embodiment of the present disclosure will be described. For the elements whose actions or functions are the same as those of the first embodiment in the aspects exemplified below, the reference numerals used in the description of the first embodiment will be diverted and detailed description of each will be omitted as appropriate.

FIG. 13 is a schematic diagram illustrating a configuration example of an ink jet system 10A according to a second embodiment. The ink jet system 10A is configured in the same manner as the above-described first embodiment except that the ink discharge devices 100A_1 to 100A_3 and the first processing devices 200A_1 to 200A_3 are provided in place of the ink discharge devices 100_1 to 100_3 and the first processing devices 200_1 to 200_3.

The ink discharge device 100A_1 is communicably coupled to the first processing device 200A_1 and is communicably coupled to the server 300 via the communication network NW. The ink discharge device 100A_2 is communicably coupled to the first processing device 200A_2 and is communicably coupled to the server 300 via the communica-

cation network NW. The ink discharge device 100A_3 is communicably coupled to the first processing device 200A_3 and is communicably coupled to the server 300 via the communication network NW. As described above, the ink discharge devices 100A_1 to 100A_3 correspond to each of the first processing devices 200A_1 to 200A_3, are communicably coupled to the first processing devices 200A_1 to 200A_3, and are communicably coupled to the server 300 via the communication network NW. In the following, each of the ink discharge devices 100A_1 to 100A_3 may be referred to as an ink discharge device 100A, without distinguishing the ink discharge devices 100A_1 to 100A_3. Each of the first processing devices 200A_1 to 200A_3 may be referred to as a first processing device 200A, without distinguishing the first processing devices 200A_1 to 200A_3.

In the example illustrated in FIG. 13, the number of each of the ink discharge device 100A and the first processing device 200A included in the ink jet system 10A is three, but the number is not limited thereto, and may be one, two, or four or more. That is, the set of the ink discharge device 100A and the first processing device 200A is not limited to three sets, and may be one set, two sets, or four sets or more.

The ink discharge device 100A is configured in the same manner as the ink discharge device 100 of the first embodiment described above, except that the head unit 110A is provided in place of the head unit 110. The head unit 110 is the same as the head unit 110 except that a function for determining the recording condition of the print processing is added. The details of the ink discharge device 100A will be described later with reference to FIG. 14.

The ink discharge device 100A outputs the output information D1 to the server 300 and inputs the input information D2 from the server 300. The ink discharge device 100A determines the recording condition of the print processing based on the input information D2.

The first processing device 200A is configured in the same manner as the first processing device 200 of the first embodiment described above, except that the function of determining the recording condition of the print processing is omitted.

FIG. 14 is a schematic diagram illustrating a configuration example of the ink discharge device 100A used in the ink jet system 10A according to the second embodiment. As illustrated in FIG. 14, the head unit 110A included in the ink discharge device 100A is configured in the same manner as the head unit 110 of the first embodiment except that the control module 110c is provided in place of the control module 110b. The control module 110c is configured in the same manner as the control module 110b except that the communication device 115, the storage circuit 116, and the processing circuit 117 are added.

The communication device 115 is a circuit capable of communicating with the server 300. For example, the communication device 115 is an interface such as a wireless or wired LAN or USB. The communication device 115 transmits the output information D1 and receives the input information D2 by communicating with the server 300. That is, the communication device 115 functions as the first coupling portion 115a that is communicably coupled to the server 300, similar to the first coupling portion 231 of the first embodiment.

The storage circuit 116 is a device that stores various programs executed by the processing circuit 117 and various data processed by the processing circuit 117. The storage circuit 116 has, for example, a semiconductor memory.

The storage circuit 116 stores the same information DG as in FIG. 4 described above. That is, the program PG1, the output information D1, and the input information D2 are stored in the storage circuit 116.

The processing circuit 117 is a device having a function of controlling each part of the control module 110c and a function of processing various data. The processing circuit 117 includes, for example, one or more processors such as a CPU. The processing circuit 117 may be integrally configured with the storage circuit 116, and may be configured to include hardware such as a DSP, an ASIC, a PLD, or an FPGA, for example.

The processing circuit 117 functions as an acquisition portion 117a, a first output portion 117b, a first input portion 117c, and a determination portion 117d by reading the program PG1 from the storage circuit 116 and executing the program PG1.

The acquisition portion 117a acquires the output information D1, similarly to in the acquisition portion 251 of the first embodiment. The first output portion 117b outputs the output information D1 via the first coupling portion 115a, similarly to the first output portion 252 of the first embodiment. The input information D2 is input to the first input portion 117c via the first coupling portion 115a, similarly to the first input portion 253 of the first embodiment. The determination portion 117d determines the recording condition of the print processing based on the input information D2, as in the determination portion 254 of the first embodiment.

FIG. 15 is a flowchart illustrating the processing of the ink jet system 10A according to the second embodiment. In the ink jet system 10A, first, as illustrated in FIG. 15, in step S201, the ink discharge device 100A acquires the output information D1. In step S202, the ink discharge device 100A outputs the output information D1 to the server 300.

Next, in step S203, the server 300 inputs the output information D1. In step S204, the server 300 generates the input information D2 based on the output information D1. Thereafter, in step S205, the server 300 outputs the input information D2 to the ink discharge device 100A.

Next, in step S206, the ink discharge device 100A inputs the input information D2. In step S207, the ink discharge device 100A determines the recording condition of the print processing based on the input information D2.

According to the second embodiment as described above, the recording condition of the print processing can be determined while reducing the burden on the printer manufacturer, similarly to the first embodiment. In the present embodiment, as described above, each of the first input portion 117c and the first coupling portion 115a is provided in the ink discharge device 100A. Therefore, the input information D2 from the server 300 can be input to the ink discharge device 100A. Therefore, by providing the determination portion 117d in the ink discharge device 100A, the information regarding the recording condition of the print processing determined by the determination portion 117d can be used in the ink discharge device 100A. In addition, since it is not necessary to incorporate the program for determining the recording condition of the print processing into the first processing device 200A, the burden on the manufacturer or the user of the printer main body can be reduced in this respect as well.

3. Third Embodiment

Hereinafter, the third embodiment of the present disclosure will be described. For the elements whose actions or

functions are the same as those of the first embodiment in the aspects exemplified below, the reference numerals used in the description of the first embodiment will be diverted and detailed description of each will be omitted as appropriate.

FIG. 16 is a schematic diagram illustrating a configuration example of an ink jet system 10B according to a third embodiment. The ink jet system 10B is configured in the same manner as the above-described first embodiment except that the first processing devices 200B_1 to 200B_3 are provided in place of the first processing devices 200_1 to 200_3 and the second processing devices 500_1 to 500_3 are added.

The second processing device 500_1 is communicably coupled to the first processing device 200B_1 and is communicably coupled to the server 300 via the communication network NW. The second processing device 500_2 is communicably coupled to the first processing device 200B_2 and is communicably coupled to the server 300 via the communication network NW. The second processing device 500_3 is communicably coupled to the first processing device 200B_3 and is communicably coupled to the server 300 via the communication network NW. As described above, the second processing devices 500_1 to 500_3 correspond to each of the first processing devices 200B_1 to 200B_3, are communicably coupled to the first processing devices 200B_1 to 200B_3, and are communicably coupled to the server 300 via the communication network NW. In the following, each of the second processing devices 500_1 to 500_3 may be referred to as a second processing device 500, without distinguishing the second processing devices 500_1 to 500_3. Each of the first processing devices 200B_1 to 200B_3 may be referred to as a first processing device 200B, without distinguishing the first processing devices 200B_1 to 200B_3.

In the example illustrated in FIG. 16, the number of each of the second processing device 500, the ink discharge device 100, and the first processing device 200B included in the ink jet system 10B is three, but the number is not limited thereto, and may be one, two, or four or more. That is, the set of the second processing device 500, the ink discharge device 100, and the first processing device 200B is not limited to three sets, and may be one set, two sets, or four sets or more.

The first processing device 200B is configured in the same manner as the first processing device 200 of the first embodiment except that the first processing device 200B is communicably coupled to each of the second processing device 500 and the ink discharge device 100.

The second processing device 500 is a mobile terminal such as a smart phone or a tablet terminal, and is configured to be able to communicate with each of the server 300 and the first processing device 200B. The second processing device 500 acquires the output information D1, outputs the output information D1 to the server 300, and inputs the input information D2 from the server 300.

The first processing device 200B is configured in the same manner as the first processing device 200 of the first embodiment. However, the first processing device 200B uses the determination portion 254 without using the acquisition portion 251, the first output portion 252, and the first input portion 253 of the acquisition portion 251, the first output portion 252, the first input portion 253, and the determination portion 254. Therefore, in the first processing device 200B, at least one of the acquisition portion 251, the first output portion 252, and the first input portion 253 may be omitted.

FIG. 17 is a schematic diagram illustrating a configuration example of a second processing device 500 used in the ink jet system 10B according to the third embodiment. The second processing device 500 includes a display device 510, an input device 520, a communication device 530, a storage circuit 540, and a processing circuit 550. These components are communicably coupled to each other.

The display device 510 displays various images under the control of the processing circuit 550. Here, the display device 510 includes various display panels such as a liquid crystal display panel or an organic electro-luminescence (EL) display panel, for example.

The input device 520 is a device that receives an operation from the user. For example, the input device 520 includes a pointing device such as a touch panel. Here, when the input device 520 includes a touch panel, the input device 520 is integrally configured with the display device 510.

The communication device 530 is a circuit capable of communicating with each of the first processing device 200B and the server 300. The communication device 530 is an interface for short-range wireless communication such as near field communication (NFC), Bluetooth low energy (BLE), Wi-Fi or Bluetooth, wireless or wired LAN, USB, or the like. NFC, BLE, Wi-Fi, and Bluetooth are registered trademarks.

The communication device 530 transmits the output information D1 and receives the input information D2 by communicating with the server 300. That is, the communication device 530 functions as a first coupling portion 531 that is communicably coupled to the server 300. In addition, the communication device 530 functions as a short-distance coupling portion 532 that is communicably coupled to the first processing device 200B by short-range wireless communication, and the input information D2 is transmitted to the first processing device 200B by the function. The communication device 530 may be integrated with the processing circuit 550.

The storage circuit 540 is a device that stores various programs executed by the processing circuit 550 and various data processed by the processing circuit 550. The storage circuit 540 has, for example, a semiconductor memory.

The storage circuit 540 of the present embodiment stores the program PG1, the output information D1, and the input information D2.

The processing circuit 550 is a device having a function of controlling each part of the second processing device 500 and a function of processing various data. The processing circuit 550 includes, for example, one or more processors such as a CPU. A part or all of the functions of the processing circuit 550 may be realized by hardware such as DSP, ASIC, PLD, and FPGA.

The processing circuit 550 functions as an acquisition portion 551, a first output portion 552, and a first input portion 553 by reading the program PG1 from the storage circuit 540 and executing the program PG1. In the present embodiment, the program PG1 stored in the storage circuit 540 does not realize the function corresponding to the determination portion 254 of the first embodiment in the processing circuit 550, but may realize the function corresponding to the determination portion 254 in the processing circuit 550. When the function corresponding to the determination portion 254 is realized in the processing circuit 550, the recording condition of the print processing may be determined by the second processing device 500 instead of the first processing device 200B.

The acquisition portion 551 acquires the output information D1, similarly to the acquisition portion 251 of the first

embodiment. In the present embodiment, as will be described later with reference to FIGS. 19A to 20B, an image for a GUI for acquiring the output information D1 is displayed on the display device 510, and the acquisition portion 251 acquires the first output information D1a, the second output information D1b, and the third output information D1c based on the input result to the input device 520.

The first output portion 552 outputs the output information D1 via the first coupling portion 531. For example, the first output portion 552 causes the server 300 to output the output information D1 to the first coupling portion 531 using an instruction or the like by the user using the input device 520 as a trigger.

The input information D2 is input to the first input portion 553 via the first coupling portion 531. For example, the input information D2 is input from the server 300 to the first input portion 553 via the first coupling portion 531 using an instruction or the like by the user using the input device 520 as a trigger.

FIG. 18 is a flowchart illustrating the processing of the ink jet system 10B according to the third embodiment. In the ink jet system 10B, first, as illustrated in FIG. 19A, in step S301, the second processing device 500 acquires the output information D1. In step S302, the second processing device 500 outputs the output information D1 to the server 300.

Next, in step S303, the server 300 inputs the output information D1. In step S304, the server 300 generates the input information D2 based on the output information D1. Thereafter, in step S305, the server 300 outputs the input information D2 to the second processing device 500.

Next, in step S306, the second processing device 500 inputs the input information D2. In step S307, the second processing device 500 outputs the input information D2 to the first processing device 200B.

Next, in step S308, the first processing device 200B inputs the input information D2. In step S309, the first processing device 200B determines the recording condition of the print processing based on the input information D2.

Hereinafter, the transition of the display of the second processing device 500 in the processing illustrated in FIG. 18 will be described with reference to FIGS. 19A to 20B. FIGS. 19A to 20B are diagrams for describing the transition of the display of the second processing device 500. In the example illustrated in FIGS. 19A to 20B, the input device 520 includes a touch panel 521, a selection button 522, and a determination button 523. The touch panel 521 is laminated on the display device 510, and receives input by, for example, a finger of the user of the second processing device 500 or an indicator such as a touch pen. The selection button 522 is, for example, a cross key, and receives an operation of selecting an item displayed on the display device 510. The determination button 523 receives, for example, an operation of confirming the input content.

In step S301 described above, first, as illustrated on the upper left side in FIG. 19A, the images G1 to G3 are displayed on the display device 510. The image G1 displays the content inquiring whether or not to execute the processing of determining the recording condition of the print processing. The image G2 is an image for receiving that the processing of determining the recording condition of the print processing is not executed. The image G3 is an image for receiving that the processing of determining the recording condition of the print processing is executed.

When the image G2 is selected by the operation of the selection button 522, and then the determination button 523 is pressed in the selected state, the images G4 to G7 are displayed on the display device 510 as illustrated on the

upper right side in FIG. 19A. The image G4 displays the content prompting the input of data or the like possessed by the operator of the second processing device 500 as information necessary for determining the recording condition of the print processing. The image G5 is an image for receiving the input of a data file used for determining the scanning speed of the head unit 110. The image G6 is an image for receiving the input of a data file used for determining the gap between the head unit 110 and the medium. The image G7 is an image for receiving the input of the data file used for determining the drive timing of the drive element 111f. By the above operations on the images G5 to G7, the data file necessary for determining the recording condition of the print processing is input. As a result, the recording condition of the print processing can be determined by using the data or the like possessed by the operator of the second processing device 500.

On the other hand, when the image G3 is selected by the operation of the selection button 522, and then the determination button 523 is pressed in the selected state, the images G9 to G11 are displayed on the display device 510 as illustrated on the lower left side in FIG. 19B. The image G9 displays the content prompting the input of the identification information of the head unit 110. In the example illustrated in FIG. 19B, the input of the product name is prompted as the identification information. The image G10 is an image for receiving the selection of one of the plurality of pieces of identification information. In the example illustrated in FIG. 19B, "Head A", "Head B", "Head C", and "Others" are displayed as the product names that are the plurality of pieces of identification information. The image G11 is an image for receiving an operation for determining the input of the identification information selected in the image G10.

When one of the plurality of pieces of identification information illustrated on the image G10 and the image G11 are selected by the operation of the selection button 522, and then the determination button 523 is pressed in the selected state, the selected identification information is acquired by the second processing device 500 as the first output information D1a. When the operation of the image G11 is performed in a state where "Others" illustrated in the image G10 is selected, processing of changing the plurality of product names illustrated in the image G10 to a plurality of product names other than "Head A", "Head B", and "Head C" may be performed. In this case, one of the plurality of product names can be selected.

Next, as illustrated in the lower center in FIG. 19B, the images G12 to G14 are displayed on the display device 510. The image G12 displays the content prompting the input of the ink manufacturer name. The image G13 is an image for receiving the selection of one of a plurality of ink manufacturers. In the example illustrated in FIG. 19B, "Company A", "Company B", "Company C", and "Others" are displayed as the plurality of ink manufacturers. Here, one of "Company A", "Company B" and "Company C", for example, "Company A" is a manufacturer of the head unit 110. The image G14 is an image for receiving an operation for determining the input of the manufacturer name selected in the image G13.

When one of the plurality of manufacturers illustrated on the image G13 and the image G14 are selected by the operation of the selection button 522, and then the determination button 523 is pressed in the selected state, the images G15 to G17 are displayed on the display device 510 as illustrated on the lower right side in FIG. 19B. When the operation of the image G14 is performed in a state where "Others" illustrated in the image G13 is selected, processing

of changing the names of the plurality of manufacturers illustrated in the image G13 to a plurality of manufacturer names other than "Company A", "Company B", and "Company C" may be performed. In this case, one of the plurality of manufacturer names can be selected.

The image G15 displays the content prompting the input of the product name of the ink. The image G16 is an image for receiving the selection of one of the plurality of product names of the manufacturers selected from the plurality of manufacturers illustrated in the image G13. In the example illustrated in FIG. 19B, "Ink A", "Ink B", "Ink C" and "Others" are displayed as the plurality of product names. The image G17 is an image for receiving an operation for determining the input of the product name selected in the image G16.

When one of the plurality of product names illustrated on the image G16 and the image G17 are selected by the operation of the selection button 522, and then the determination button 523 is pressed in the selected state, the information on the selected product name is acquired by the second processing device 500 as the second output information D1b. When the operation of the image G17 is performed in a state where "Others" illustrated in the image G16 is selected, processing of changing the plurality of product names illustrated in the image G16 to a plurality of product names other than "Ink A", "Ink B", and "Ink C" may be performed. In this case, one of the plurality of product names can be selected.

Next, as illustrated on the upper left side in FIG. 20A, the images G18 to G20 are displayed on the display device 510. The image G18 displays the content prompting the input of the operating environment temperature of the head unit 110. The image G19 is an image for receiving the selection of one of a plurality of temperature ranges. In the example illustrated in FIG. 20A, "less than 0°C.", "0°C. to 15°C.", "15°C. to 30°C." and "30°C. or higher" are displayed as the plurality of temperature ranges. The image G20 is an image for receiving an operation for determining the input of the temperature range selected in the image G19.

When one of the plurality of temperature ranges illustrated on the image G19 and the image G20 are selected by the operation of the selection button 522, and then the determination button 523 is pressed in the selected state, the information on the selected temperature range is acquired by the second processing device 500 as the third output information D1c. The image G19 may be a display in which a temperature range subdivided than the example illustrated in FIG. 20A can be selected, or may be a display for inputting the operating environment temperature of the head unit 110 as a numerical value.

As described above, in the above-described step S301, the output information D1 including the first output information D1a, the second output information D1b, and the third output information D1c is acquired. The acquisition order of the first output information D1a, the second output information D1b, and the third output information D1c is not limited to the examples illustrated in FIGS. 19A to 20B, and is optional.

After the output information D1 is acquired, the images G24 to G26 are displayed on the display device 510 as illustrated on the upper right side in FIG. 20A. The image G24 displays the content inquiring whether or not to allow the output information D1 to be transmitted to the server 300. The image G25 is an image for receiving that the output information D1 is not permitted to be transmitted to the

server 300. The image G26 is an image for receiving that the output information D1 is permitted to be transmitted to the server 300.

When the image G25 is selected by the operation of the selection button 522, and then the determination button 523 is pressed in the selected state, the display device 510 returns to the display state on the upper left side in FIG. 19A described above.

On the other hand, when the image G26 is selected by the operation of the selection button 522, and then the determination button 523 is pressed in the selected state, the output information D1 is transmitted to the server 300. As a result, the above-described step S302 is executed. Thereafter, as illustrated in the middle part of FIG. 20B, the image G27 is displayed on the display device 510. The image G27 indicates that the input information D2 is being calculated by the server 300.

When the input information D2 can be generated by the server 300, the images G28 to G32 are displayed on the display device 510 as illustrated on the lower left side in FIG. 20B. The image G28 is an image illustrating that the input information D2 is input to the second processing device 500. The image G29 is an image illustrating an outline of the content of the input information D2 input to the second processing device 500. The image G30 is an image for receiving an instruction to display details (preview, predicted evaluation value, and the like) of the content of the input information D2 input to the second processing device 500. The image G31 is an image for receiving the change of the content of the image G29 to the content of the other input information D2. The image G32 is an image for receiving that the input information D2 input to the second processing device 500 is adopted as the information used for determining the recording condition of the print processing.

When the image G32 is selected by the operation of the selection button 522, and then the determination button 523 is pressed in the selected state, the input information D2 displayed on the image G29 is transmitted to the first processing device 200B. As a result, the above-described step S307 is executed.

On the other hand, when the input information D2 cannot be generated by the server 300, the images G33 to G36 are displayed on the display device 510 as illustrated on the lower right side in FIG. 20B. The image G33 is an image illustrating that the input information D2 cannot be input to the second processing device 500. The image G34 is a display of the content inquiring the owner of the server 300 whether or not to request the generation of the input information D2. The image G35 is an image for receiving that the owner of the server 300 is requested to generate the input information D2. The image G36 is an image for receiving that the owner of the server 300 is not requested to generate the input information D2 again.

When the image G35 is selected by the operation of the selection button 522, and then the determination button 523 is pressed in the selected state, the display of the display device 510 transitions to a display for inputting various information (email address, name, and the like) necessary for requesting the owner of the server 300 to generate the input information D2. On the other hand, when the image G36 is selected by the operation of the selection button 522, and then the determination button 523 is pressed in the selected state, the display device 510 returns to the display state on the upper left side in FIG. 19A described above.

According to the third embodiment as described above, the recording condition of the print processing can be determined while reducing the burden on the printer manu-

facturer, similarly to the first embodiment or the second embodiment. In the present embodiment, as described above, the ink jet system 10B includes the second processing device 500. The second processing device 500 is communicably coupled to the first processing device 200. The first input portion 553 and the first coupling portion 531 are provided in the second processing device 500. Therefore, the input information D2 from the server 300 can be input to the second processing device 500. In addition, the determination portion 254 can be provided in the first processing device 200B. The recording condition of the print processing determined by the determination portion 254 can be set by the first processing device 200B. The second processing device 500 may be provided with a functional portion corresponding to the determination portion 254. In this case, the information regarding the recording condition of the print processing determined by the functional portion can be input from the second processing device 500 to the first processing device 200.

In addition, as described above, the first processing device 200 and the second processing device 500 are communicably coupled to each other by short-range wireless communication. Therefore, the input information D2 can be input from the second processing device 500 to the first processing device 200B in a simple communication environment. When the second processing device 500 is provided with a functional portion corresponding to the determination portion 254, information regarding the recording condition of the print processing determined by the functional portion can be input from the second processing device 500 to the first processing device 200B.

4. Fourth Embodiment

Hereinafter, the fourth embodiment of the present disclosure will be described. For the elements whose actions or functions are the same as those of the first embodiment in the aspects exemplified below, the reference numerals used in the description of the first embodiment will be diverted and detailed description of each will be omitted as appropriate.

FIG. 21 is a schematic diagram illustrating a configuration example of an ink jet system 10C according to a fourth embodiment. The ink jet system 10C is configured in the same manner as the first embodiment described above, except that the ink discharge devices 100C_1 to 100C_3 and the first processing devices 200A_1 to 200A_3 are provided in place of the ink discharge devices 100_1 to 100_3 and the first processing devices 200_1 to 200_3, and the second processing devices 500_1 to 500_3 are added. That is, the ink jet system 10C is configured in the same manner as the third embodiment described above except that the ink discharge devices 100C_1 to 100C_3 and the first processing devices 200A_1 to 200A_3 are provided in place of the ink discharge devices 100_1 to 100_3 and the first processing devices 200B_1 to 200B_3. The first processing device 200A is configured in the same manner as the first processing device 200A of the second embodiment.

In the present embodiment, the second processing device 500_1 is communicably coupled to the ink discharge device 100C_1 and is communicably coupled to the server 300 via the communication network NW. The second processing device 500_2 is communicably coupled to the ink discharge device 100C_2 and is communicably coupled to the server 300 via the communication network NW. The second processing device 500_3 is communicably coupled to the ink discharge device 100C_3 and is communicably coupled to the server 300 via the communication network NW. As

described above, the second processing devices **500_1** to **500_3** correspond to each of the ink discharge devices **100C_1** to **100C_3**, are communicably coupled to the ink discharge devices **100C_1** to **100C_3**, and are communicably coupled to the server **300** via the communication network **NW**. In the following, each of the ink discharge devices **100C_1** to **100C_3** may be referred to as an ink discharge device **100C**, without distinguishing the ink discharge devices **100C_1** to **100C_3**.

In the example illustrated in FIG. 21, the number of each of the second processing device **500**, the ink discharge device **100C**, and the first processing device **200A** included in the ink jet system **10C** is three, but the number is not limited thereto, and may be one, two, or four or more. That is, the set of the second processing device **500**, the ink discharge device **100C**, and the first processing device **200A** is not limited to three sets, and may be one set, two sets, or four sets or more.

The ink discharge device **100C** is configured in the same manner as the ink discharge device **100A** of the second embodiment except that the ink discharge device **100C** can communicate with each of the server **300** and the first processing device **200A**.

FIG. 22 is a schematic diagram illustrating a configuration example of an ink discharge device **100C** used in the ink jet system **10C** according to the fourth embodiment. As illustrated in FIG. 22, the ink discharge device **100C** is configured in the same manner as the ink discharge device **100A** of the second embodiment except that the head unit **110C** is provided in place of the head unit **110A**. The head unit **110C** is configured in the same manner as the head unit **110A** except that the control module **110d** is provided in place of the control module **110c**. The control module **110d** is the same as the control module **110c** except that the communication device **115** functions as a short-distance coupling portion **115b** and the processing circuit **117** functions as the acquisition portion **117a** and the determination portion **117d**.

In the present embodiment, the communication device **115** is a circuit capable of communicating with the second processing device **500**. For example, the communication device **115** is an interface for short-range wireless communication such as Wi-Fi or Bluetooth. That is, the communication device **115** functions as the short-distance coupling portion **115b** that is communicably coupled to the short-distance coupling portion **532** of the second processing device **500** by short-range wireless communication, and outputs the output information **D1** to the second processing device **500** or inputs the input information **D2** from the second processing device **500** by the function.

FIG. 23 is a flowchart illustrating the processing of the ink jet system **10C** according to the fourth embodiment. In the ink jet system **10C**, first, as illustrated in FIG. 23, the ink discharge device **100C** acquires the output information **D1** in step **S401**. In step **S402**, the ink discharge device **100C** outputs the output information **D1** to the second processing device **500** by the function.

Next, in step **S403**, the second processing device **500** inputs the output information **D1**. In step **S404**, the second processing device **500** outputs the output information **D1** to the server **300**.

Next, in step **S405**, the server **300** inputs the output information **D1**. In step **S406**, the server **300** generates the input information **D2** based on the output information **D1**. Thereafter, in step **S407**, the server **300** outputs the input information **D2** to the second processing device **500**.

Next, in step **S408**, the second processing device **500** inputs the input information **D2**. In step **S409**, the second

processing device **500** outputs the input information **D2** to the ink discharge device **100C**.

Next, in step **S410**, the ink discharge device **100C** inputs the input information **D2**. In step **S411**, the ink discharge device **100C** determines the recording condition of the print processing based on the input information **D2**.

According to the fourth embodiment as described above, the recording condition of the print processing can be determined while reducing the burden on the printer manufacturer, similarly to the first to third embodiments. In the present embodiment, as described above, the ink jet system **10C** includes the second processing device **500**. The second processing device **500** is communicably coupled to the ink discharge device **100**. The first input portion **553** and the first coupling portion **531** are provided in the second processing device **500**. Therefore, the input information **D2** from the server **300** can be input to the second processing device **500**. In addition, the ink discharge device **100C** can be provided with the determination portion **117d**. The information regarding the recording condition of the print processing determined by the determination portion **117d** can be used in the ink discharge device **100**. The second processing device **500** may be provided with a functional portion corresponding to the determination portion **117d**. In this case, the information regarding the recording condition of the print processing determined by the functional portion can be input from the second processing device **500** to the ink discharge device **100**.

In addition, as described above, the ink discharge device **100** and the second processing device **500** are communicably coupled to each other by short-range wireless communication. Therefore, in a simple communication environment, the output information **D1** can be output from the ink discharge device **100C** to the second processing device **500**, and the input information **D2** from the second processing device **500** can be input to the ink discharge device **100C**. When the second processing device **500** is provided with a functional portion corresponding to the determination portion **254**, information regarding the recording condition of the print processing determined by the functional portion can be input from the second processing device **500** to the ink discharge device **100C**.

5. Modification Example

The ink jet system of the present disclosure has been described above based on the illustrated embodiment, but the present disclosure is not limited thereto. In addition, the configuration of each part of the present disclosure can be replaced with a predetermined configuration that exhibits the same function as that of the above-described embodiment, or a predetermined configuration can be added.

5-1. Modification Example 1

In the above-described embodiment, the case where the output information **D1** includes both the first output information **D1a** and the second output information **D1b** is exemplified, but the present disclosure is not limited thereto. For example, one of the first output information **D1a** and the second output information **D1b** may be omitted. In addition, when the type of the ink discharge head **110a** or the head unit **110** is known on the server side, the first output information **D1a** may not be included in the output information **D1**. In addition, the output information **D1** may not include the third output information **D1c**. In this case, for example, the

41

temperature of the ink is estimated from the model of the head unit **110** on the server side.

5-2. Modification Example 2

In the above-described embodiment, the configuration in which the input information **D2** includes the first input information **D2a**, the second input information **D2b**, and the third input information **D2c** is exemplified, but the present disclosure is not limited to the configuration. For example, among the first input information **D2a**, the second input information **D2b**, and the third input information **D2c**, the information already shared by both the printer manufacturer and the head manufacturer may be omitted.

5-3. Modification Example 3

In the above-described embodiment, a configuration in which the server **300** is a cloud server is exemplified, but the present disclosure is not limited to the configuration. For example, the server **300** may be a server other than a cloud server or a virtual server, or may be an on-premises server.

5-4. Modification Example 4

In the above-described embodiment, the configuration in which the drive element **111f** is a piezoelectric element is exemplified, but the present disclosure is not limited thereto, and for example, the drive element **111f** may be a heater that heats the ink in the pressure chamber **C**. That is, the drive method of the head chip **111** is not limited to the piezoelectric method, and may be, for example, a thermal method.

What is claimed is:

1. An ink jet system comprising:

a head unit that includes a nozzle discharging ink, a pressure chamber communicating with the nozzle, and a drive element applying pressure fluctuation to the ink in the pressure chamber by supplying a drive pulse; an acquisition portion that acquires output information including one or both of first output information regarding the head unit and second output information regarding the ink used for the head unit; a first coupling portion that is communicably network-coupled to a server; a first output portion that outputs the output information to the server via the first coupling portion; a first input portion to which input information is input from the server via the first coupling portion; and a determination portion that determines a drive timing of the drive element based on the input information, wherein the server includes a storage portion in which correspondence information regarding a correspondence relationship between the output information and a recording condition of print processing to be executed is stored in advance, and a calculation portion that performs a calculation generating the input information based on the output information and the correspondence information.

2. The ink jet system according to claim 1, wherein the output information includes information regarding a discharge characteristic of the head unit as the first output information, when the discharge characteristic indicated by the first output information is a first discharge characteristic, the drive timing is a first drive timing, and when the discharge characteristic indicated by the first output information is a second discharge characteristic

42

higher than the first discharge characteristic, the drive timing is a second drive timing later than the first drive timing.

3. The ink jet system according to claim 1, wherein the output information includes information regarding a viscosity of the ink as the second output information, when the viscosity indicated by the second output information is a first viscosity, the drive timing is a third drive timing, and

when the viscosity indicated by the second output information is a second viscosity higher than the first viscosity, the drive timing is a fourth drive timing earlier than the third drive timing.

4. The ink jet system according to claim 1, wherein the output information includes third output information regarding a temperature of the ink used for the head unit,

when the temperature indicated by the third output information is a first temperature, the drive timing is a fifth drive timing, and

when the temperature indicated by the third output information is a second temperature higher than the first temperature, the drive timing is a sixth drive timing later than the fifth drive timing.

5. The ink jet system according to claim 1, further comprising:

a reception portion that receives an instruction by a user as to whether or not to execute print processing under a recording condition indicated by the input information, wherein

the determination portion determines

to execute the print processing under the recording condition indicated by the input information, when the reception portion receives an instruction to execute the print processing under the recording condition indicated by the input information, and to execute print processing under another recording condition input by the user, when the reception portion receives an instruction not to execute the print processing under the recording condition indicated by the input information.

6. The ink jet system according to claim 1, further comprising:

an ink discharge device that includes the head unit; a first processing device coupled to the ink discharge device, that includes a display portion displaying information regarding the ink discharge device; and the server.

7. An ink jet system comprising:

a head unit that includes a nozzle discharging ink, a pressure chamber communicating with the nozzle, and a drive element applying pressure fluctuation to the ink in the pressure chamber by supplying a drive pulse; an acquisition portion that acquires output information including one or both of first output information regarding the head unit and second output information regarding the ink used for the head unit;

a first coupling portion that is communicably network-coupled to a server;

a first output portion that outputs the output information to the server via the first coupling portion;

a first input portion to which input information is input from the server via the first coupling portion; and a determination portion that determines a drive timing of the drive element based on the input information, wherein

43

the output information includes information regarding a discharge characteristic of the head unit as the first output information, when the discharge characteristic indicated by the first output information is a first discharge characteristic, the drive timing is a first drive timing, and when the discharge characteristic indicated by the first output information is a second discharge characteristic higher than the first discharge characteristic, the drive timing is a second drive timing later than the first drive timing. 10

8. An ink jet system comprising:

a head unit that includes a nozzle discharging ink, a pressure chamber communicating with the nozzle, and a drive element applying pressure fluctuation to the ink in the pressure chamber by supplying a drive pulse; an acquisition portion that acquires output information including one or both of first output information regarding the head unit and second output information regarding the ink used for the head unit; 15

44

a first coupling portion that is communicably network-coupled to a server; a first output portion that outputs the output information to the server via the first coupling portion; a first input portion to which input information is input from the server via the first coupling portion; and a determination portion that determines a drive timing of the drive element based on the input information, wherein

the output information includes information regarding a viscosity of the ink as the second output information, when the viscosity indicated by the second output information is a first viscosity, the drive timing is a third drive timing, and

when the viscosity indicated by the second output information is a second viscosity higher than the first viscosity, the drive timing is a fourth drive timing earlier than the third drive timing.
